**CROSSED-FIELD DISCHARGE DEVICES AND
OSCILLATORS AND AMPLIFIERS INCORPORATING
THE SAME**

This is a continuing application of applicant's copending application, Ser. No. 483,733, filed Aug. 30, 1965, now abandoned.

The present invention relates to improved crossed-field discharge devices and microwave circuits incorporating the same including microwave oscillator circuits and microwave amplifier circuits.

It is a general object of the invention to provide new and improved crossed-field discharge devices for use at microwave frequencies, which devices are of exceedingly simple and economical construction and arrangement.

Another object of the invention is to provide improved crossed-field discharge devices of the type set forth which are particularly adapted for operation with relatively low voltage operating potentials applied thereto.

Another object of the invention is to provide improved crossed-field discharge devices of the type set forth which can provide a high output of microwave energy in proportion to the physical dimensions thereof, whereby to permit the miniaturization of microwave circuits embodying the improved crossed-field discharge devices of the present invention.

Another object of the invention is to provide a crossed-field discharge device of the type set forth including an anode structure defining an axially extending space, a plurality of axially extending segments on the anode structure and projecting radially into the axially extending space and providing a corresponding plurality of axially extending anode recesses therebetween, a plurality of rods respectively disposed in the anode recesses and respectively spaced from the adjacent ones of the anode segments with the rods electrically interconnected at corresponding ends thereof, an axially extending cathode structure disposed in the axially extending space and cooperating with the anode structure to define an axially extending annular interaction space, the cathode structure including an electron emissive element disposed within the anode structure and adjacent to the inner portion of the interaction space, and end structures enclosing the ends of the anode structure and the axially extending space.

Another object of the invention is to provide a crossed-field discharge device of the type set forth, wherein two pole pieces are respectively arranged adjacent to the opposite ends of the anode structure for establishing a unidirectional magnetic field extending axially through the interaction space.

In connection with the foregoing object, it is another object of the invention to provide an improved crossed-field discharge device of the type set forth, wherein the pole pieces include portions overlying and in axial alignment with the anode recesses, and wherein the rods are respectively mounted on those portions of the pole pieces overlying the anode recesses, the pole pieces further electrically interconnecting the rods and having a connector attached thereto and extending through the associated end structure to provide electrical connection to external circuits for the rods.

Another object of the invention is to provide a crossed-field discharge device of the type set forth, wherein the anode structure and the rods in the operation of the device cooperate to provide a portion of a coaxial transmission line for accommodating an axially extending RF wave therein, whereby there are RF electrical fields between the anode structure and the rods and extending inwardly into the interaction space and having associated therewith annular RF magnetic fields about the rods and extending inwardly into the interaction space.

Another object of the invention is to provide an improved crossed-field discharge device of the type set forth, wherein the rods and the cathode structure in the operation of the device cooperate to provide a portion of a coaxial transmission line for accommodating an axially extending RF wave therein, whereby there are RF electrical fields between the rods and the cathode structure and extending into the interaction space and having associated therewith annular RF magnetic fields extending into the interaction space.

Another object of the invention is to provide an improved crossed-field discharge device of the type set forth wherein the anode structure and the cathode structure in the operation of the device also cooperate to provide a portion of a coaxial transmission line for accommodating an axially extending RF wave therein, whereby there are RF electrical fields between the anode structure and the cathode structure and in the interaction space and having associated therewith RF magnetic fields also in the interaction space.

10 Another object of the invention is to provide an improved crossed-field discharge device of the type set forth, wherein the radial distance between the outer surface of the cathode structure and the outermost portion of the adjacent one of the anode recesses is less than that required to accommodate a radial standing wave at an operating frequency having a wave length corresponding to twice the distance between the ends of the anode structure.

Another object of the invention is to provide an improved crossed-field discharge device of the type set forth, wherein the radial extent of the recesses is of the same order of magnitude as the circumferential widths thereof at the inner edges of the anode segments, the anode recesses being preferably rectangular in shape as viewed along the axis of the device, the anode segments also preferably extending radially inwardly beyond the innermost surfaces of the associated rods.

Another object of the invention is to provide an improved crossed-field discharge device of the type set forth, wherein the anode structure and the pole pieces and the rods and the cathode are symmetrical about a plane normal to the axis of the anode structure midway between the ends thereof.

Another object of the invention is to provide an improved crossed-field discharge device of the type set forth, wherein the cathode structure includes a plurality of circumferentially spaced electron emissive sections corresponding in number to the anode segments and respectively arranged adjacent to one of the anode segments, the electron emissive sections further preferably being circumferentially spaced apart a distance corresponding to the circumferential dimension thereof.

40 In connection with the foregoing object, it is another object of the present invention to provide in a crossed-field discharge device of the type set forth, circumferentially spaced protrusions on a cathode structure, at least the outermost surface portions of the protrusions being an electron emissive material, the emissive portions having a circumferential extent of approximately 25 percent to 60 percent of the circumferential distance between the centers of adjacent electron emissive portions, and the radial dimension of each of the protrusions preferably being greater than about 20 percent of the spacing between the anode structure and the cathode structure.

Another object of the invention is to provide an improved crossed-field discharge device of the type set forth, wherein the electron emissive portions on the cathode are symmetrically circumferentially located relative to the anode segments, and are preferably circumferentially displaced relative thereto between 0 percent and approximately 45 percent of the circumferential space between adjacent anode segments, the preferred displacement being approximately 35 percent to 45 percent.

60 Another object of the invention is to provide an improved crossed-field discharge device of the type set forth, wherein the cathode has spaced apart emissive portions thereon equal in number to the sum of the number of anode segments and the number of rods.

65 Another object of the invention is to provide an improved crossed-field discharge device of the type set forth wherein the cathode structure has a conically shaped electron emissive element disposed within the anode structure and adjacent to the inner portion of the interaction space with the axis of the emissive element extending axially of the device, the preferred shape of the emissive element being a section of a regular right cone.

70 A further object of the invention is to provide an improved microwave oscillator incorporating therein a crossed-field discharge device of the present invention, the resonant circuit

75

for the oscillator being connectable between the anode structure and the rods, or between the anode structure and the cathode structure, or between the cathode structure and the rods, the resonant circuit preferably being of the coaxial conductor type and having a wavelength corresponding to one-fourth or one-half of the wavelength of the resonant frequency thereof.

In connection with the foregoing object, it is a further object of the invention to provide an improved microwave oscillator of the type set forth, wherein the resonant circuit is tunable.

A still further object of the invention is to provide an improved microwave amplifier incorporating therein a crossed-field discharge device of the present invention.

Further features of the invention pertain to the particular arrangement of the parts whereby the above-outlined and additional operating features thereof are attained.

The invention, both as to its organization and method of operation, together with further objects and advantages thereof, will best be understood by reference to the following specification taken in connection with the accompanying drawings, in which:

FIG. 1 is a schematic and diagrammatic illustration of an oscillator circuit incorporating therein a crossed-field discharge device of the present invention;

FIG. 2 is a view in vertical section through the crossed-field discharge device of FIG. 1 and illustrating the circuit connections including the magnetic field coils for the crossed-field discharge device, the connections illustrated being for an oscillator having a one-half wavelength-tuned circuit, the tuned circuit being connected between the anode structure and the rods;

FIG. 3 is an enlarged view in vertical section through a first preferred form of the crossed-field discharge device of FIG. 2;

FIG. 4 is a further enlarged view in horizontal section through the device of FIG. 3 along the line 4-4 thereof;

FIG. 5 is a view in horizontal section through the device of FIG. 3 along the line 5-5 thereof;

FIG. 6 is a further enlarged view in horizontal section through the device of FIG. 3 along the line 6-6 thereof;

FIGS. 7 to 12, inclusive are still further enlarged views in horizontal section of a portion of FIG. 6 and illustrating the various electrical and magnetic fields present in the device during the operation thereof;

FIG. 13 is a view in vertical section similar to FIG. 2, but illustrating an oscillator circuit having a one-fourth wavelength-tuned circuit;

FIG. 14 is a view in vertical section also similar to FIG. 2 and illustrating an oscillator having a one-half wavelength-tuned circuit, the frequency of the tuned circuit being adjustable;

FIG. 15 is a view in vertical section similar to FIG. 2, but illustrating an oscillator circuit having a one-half wavelength-tuned circuit connected between the anode structure and the cathode structure;

FIGS. 16 and 17 are views similar to FIGS. 7 to 12 and illustrating certain of the electrical and magnetic fields present in the crossed-field discharge device during the operation of the circuit illustrated in FIG. 15;

FIG. 18 is a view in vertical section similar to FIG. 15, and illustrating a modification of the circuit wherein the frequency of the tuned circuit is adjustable;

FIG. 19 is a view in vertical section similar to FIG. 2, and illustrating an oscillator having a one-half wavelength tuned-circuit connected between the rods and the cathode structure of the crossed-field discharge device;

FIGS. 20 and 21 are fragmentary enlarged views in cross section similar to FIGS. 7 to 12 and illustrating certain of the electrical and magnetic fields in the crossed-field discharge device during the operation of the circuit illustrated in FIG. 19;

FIG. 22 is a view in vertical section similar to FIG. 19, but illustrating a modification of the oscillator circuit wherein a one-fourth wavelength-tuned circuit is connected between the

rods and the cathode structure of the crossed-field discharge device;

FIG. 23 is a view in vertical section also similar to FIG. 19 and illustrating an oscillator having a one-half wavelength-tuned circuit, the frequency of the tuned circuit being adjustable;

FIGS. 24 to 26, inclusive, are graphs plotting several operating characteristics of the crossed-field discharge device illustrated in FIGS. 3 to 6 of the drawings;

FIG. 27 is a schematic and diagrammatic illustration of an amplifying circuit for amplifying the output of a microwave oscillator, the amplifying circuit utilizing therein a crossed-field discharge device made in accordance with and embodying the principles of the present invention;

FIG. 28 is a view in vertical section through the crossed-field discharge device in the amplifying circuit of FIG. 27 and illustrating the circuit connections including the magnetic field coils for the crossed-field discharge device, the oscillator input circuits therefor and the output circuits therefor;

FIG. 29 is an enlarged view in vertical section through a modified form of the crossed-field discharge device illustrated in FIGS. 3 to 6;

FIG. 30 is a view in vertical section through a microwave oscillator incorporating therein yet another preferred embodiment of the crossed-field discharge device made in accordance with and embodying the principles of the present invention;

FIG. 31 is an enlarged view in vertical section through the crossed-field discharge device in the oscillator circuit of FIG. 30;

FIG. 32 is a fragmentary view in horizontal section through the crossed-field discharge device of FIG. 31 along the line 32-32 thereof;

FIG. 33 is a view in horizontal section through the crossed-field discharge device of FIG. 31 along the line 33-33 thereof;

FIG. 34 is a further enlarged view in horizontal section through the crossed-field discharge device of FIG. 31 along the line 34-34 thereof; and

FIGS. 35 to 40, inclusive, are graphs plotting several operating characteristics of the crossed-field device illustrated in FIGS. 30 to 34 of the drawings.

Referring now to FIG. 1 of the drawings, there is diagrammatically illustrated an oscillator circuit 50 embodying the features of the present invention, the oscillator circuit 50 having been illustrated as connected to a three-wire Edison network of 236 volts, single-phase, 60 cycles, AC, and including two ungrounded line conductors L1 and L2 and a grounded neutral conductor N, the three conductors mentioned being terminated at an associated electrical insulating block B. The circuit 50 also comprises a power supply 51 having a pair of input terminals 52 and 53 that are respectively connected to the conductors L1 and L2. A first pair of output terminals 54 and 55 is provided for supplying a relatively low voltage AC power for the purpose of energizing the heater of the crossed-field discharge device forming a part of the oscillator 50; and a second pair of output terminals 56 and 57 is provided for supplying a rectified and filtered DC voltage of low amplitude for supplying the DC operating potentials to the crossed-field discharge device of the circuit 50. More specifically, the input terminals 52 and 53 are connected to the output terminals 56 and 57 by a converter, the converter preferably being of the type disclosed in the copending application of James E. Staats, Ser. No. 181,144 filed Mar. 20, 1962, wherein there is disclosed a converter comprising an assembly of capacitors and rectifiers connected between the input terminals and the output terminals thereof, and characterized by the production of a DC output voltage across the output terminals thereof in response to the application of a low frequency AC input therebetween across the input terminals thereof, wherein the amplitude of the DC output voltage from the converter is approximately twice the peak value of the AC input voltage to the converter. The converter described is in fact a voltage doubler and rectifier circuit wherein the output DC potential

65

60

65

70

75

therefrom at the output terminals 56 and 57 is approximately 666 volts when the AC supply source has an R.M.S. voltage of 236 volts between the conductors L1 and L2, the 666 volts DC being the open circuit or no load value for the DC output from the power supply 51.

The oscillator circuit 50 further comprises an oscillator 100 incorporating therein a crossed-field discharge device made in accordance with and embodying the principles of the present invention, the oscillator 100 having a pair of input terminals 101 and 102 that are connected respectively to the DC output terminals 56 and 57 of the power supply 51 by means of conductors 60 and 61, respectively; the input terminal 102 is also connected by the conductor 61 to one of the low voltage AC output terminals 55 of the power supply 51. A third input terminal 103 is provided for the oscillator 100, the input terminal 103 being connected by a conductor 62 to the other low voltage AC output terminal 54 of the power supply 51. As illustrated, all of the parts of the oscillator 100 are surrounded by a metallic casing 105 to which is connected as at 106 an outer tubular conductor 107 within which is disposed an inner conductor from the input terminal 102 which forms one of the output connections for the oscillator 100. Another output connection 111 is provided for the oscillator 100, the output connection 111 being connected to the metallic casing 105 by the connection 106 and thus to the outer conductor 107. Connection is made to an output transmission line 64 including an outer tubular conductor 65 and an inner conductor 66 disposed therein, a first capacitive coupling being provided by a coupler 80 in the outer conductor 65 and a second capacitive coupling being provided by a coupler and filter assembly 83 between the terminal 102 and the inner conductor 66. The capacitive coupling provided by the couplers 80 and 83 is desirable and necessary since for safety purposes it is necessary to ground the outer conductor 65 of the transmission line 64, which grounding of the outer conductor 65 is not possible if there is a DC connection to the oscillator casing 105, the casing 105 having a potential with respect to ground because of the application of operating potentials from the voltage doubler and rectifying circuit, it being inherent in the construction and operation of the power supply 51 that neither the conductor 60 nor the conductor 61 can be grounded. Accordingly, it is also necessary and desirable that the power supply 51 and the oscillator 100 be electrically shielded by a grounded outer housing (not shown) disposed therearound, all as is fully described in the aforementioned copending application Ser. No. 181,144.

The microwave energy supplied from the oscillator 100 to the transmission line 64 may be used for any desired purpose, two typical uses of the microwave energy being illustrated in FIG. 1, the first use being illustrated in the upper right-hand portion of FIG. 1 wherein the transmission line 64 is shown coupled to an antenna of the type commonly used in search radar, the outer conductor 65 being connected to outer radiating or antenna elements 67 and the inner conductor 66 being connected to an inner radiating or antenna element 68, the antenna elements 67 and 68 serving to match the impedance of the transmission line 64 to the impedance of the atmosphere. Alternatively, the microwave energy from the oscillator 100 in the transmission line 64 may be utilized in an electronic heating apparatus such as the electronic range 70 illustrated that is especially designed for home use. More particularly, the range 70 comprises an upstanding substantially boxlike casing 71 formed of steel and housing therein a metal liner 72 defining a heating cavity therein. The metal liner 72 may also be formed of steel, and essentially comprises a boxlike structure provided with a top wall, a bottom wall, a rear wall and a pair of opposed sidewalls; whereby the liner 72 is provided with an upstanding front opening into the heating cavity defined therein, the casing 71 being provided with a front door 73 arranged in the front opening thus formed and cooperating with the liner 72. More particularly, the front door 73 is mounted adjacent to the lower end thereof upon associated hinge structure 74, and is provided adjacent to the upper end thereof with a han-

dle 75, whereby the front door 73 is movable between a substantially vertical closed position and a substantially horizontal open position with respect to the front opening provided in the liner 72. Also the front door 73 has an inner metal sheet 5 that is formed of steel and cooperates with the liner 72 entirely to close the heating cavity when the front door 73 occupies its closed position. For safety purposes, the inner liner 72 is connected by the conductor 76 to the outer casing 71 which is in turn grounded by the conductor N. The outer conductor 65 of the transmission line 64 is connected as at 78 to the casing 71 and the liner 72 of the range 70, and there is provided within the range 70 at the rear thereof a radiating element or antenna 77 that is connected as at 79 to the inner conductor 66 of the transmission line 64. Accordingly, the microwave energy within the transmission line 64 is radiated into the cooking cavity of the range 70 to provide the power for cooking materials disposed therein. It further will be understood that in a preferred embodiment of the range 70, the power supply 51 and the oscillator 100 therefor together with the transmission line 64 are all preferably disposed within a common housing that also includes the casing 71, the common housing being preferably formed of metal and grounded for safety purposes.

Further details of the construction of the oscillator 100 and the crossed-field discharge device 110 forming a part thereof will now be described with particular reference to FIGS. 2 to 6 of the drawings. The device 110 includes an anode 111, a pair of opposed pole pieces 120 having connected therebetween a plurality of rods 130, a cathode structure 140 and a pair of opposed end structures 160. The anode 111 is generally annular in shape and has a circular cross section, the outer wall 112 thereof being cylindrical and extending between a pair of parallel opposed end walls 113 and 114, there being provided interiorly of the anode an axially extending space. Provided on the inner surface of the anode 111 is a plurality of axially extending anode segments 115 that project radially into the axially extending space within the anode 111 and providing therebetween a corresponding plurality of axially extending anode recesses 116, 15 of the anode segments 115 and 15 of the corresponding recesses 116 being provided in the anode 111 as illustrated in the drawings. Each of the anode segments 115 has an axially extending inner surface 117 and a pair of outwardly directed sidewalls 118 on opposite sides thereof, the circumferential extent of the inner surface 117 being substantially less than the radial extent of the associated sidewalls 118. The outer ends of the sidewalls 118 are joined by an outer wall 119, whereby the recesses 116 are defined by the associated sidewalls 118 and the associated outer wall 119, the sidewalls 118 of the recesses 116 being disposed substantially parallel to each other and substantially normal to the associated outer wall 119, whereby each of the recesses 116 is substantially square in cross section. The anode 111 is formed of a nonmagnetic metal having good electrical conductivity and good thermal conductivity, the preferred material of construction being copper.

In order to remove heat from the anode 111 during the operation of the device 110, there is mounted upon the outer wall 112 of the anode 111 a plurality of outwardly and radially extending cooling fins 129, seven of the fins 129 being illustrated in FIG. 2 of the drawings. The fins 129 are preferably formed of a good heat-conducting material such as copper and are in both mechanical connection and heat transfer connection with the anode 111, the fins 129 preferably being brazed upon the outer wall 112 of the anode 111. The shape of the fins 129 is such that they can fit within the casing 105, there preferably being provided means for passing a cooling fluid, such as a stream of air, through the casing 105 and over the fins 129 to effect cooling thereof and a consequent removal of heat from the anode 111 and the other parts of the device 110 during the operation thereof.

Mounted adjacent to the outer ends of the anode 111 respectively are the pole pieces 120, the pole pieces 120 being identical in construction, whereby the same reference numerals have been applied to like parts of both of the pole

pieces 120. The pole pieces 120 are formed of a high magnetic permeability material such as soft iron, and are copper plated to render the outer surfaces thereof highly conductive to RF energy. As illustrated, each of the pole pieces 120 is essentially cylindrical in shape having a cylindrical outer surface 121 on the inner end of which is provided an outwardly extending projection 122. A pair of end surfaces 123 and 124 is provided on the axially disposed ends of the pole pieces 120 and another surface 125 is provided in the portion of the projection 122 disposed toward the end surface 123. Preferably the diameter of the outer surface 121 is slightly less than the diameter of the axially extending space in the anode 111, whereas the outer diameter of the projection 122 is such that the projection 122 overlies and is in axial alignment with the recesses 116 in the anode 111. Formed in the projection 122 is a plurality of openings 126 equal in number to the recesses 116, 15 as illustrated, and a corresponding number of rods 130, i.e., 15 in number, are disposed in the openings 126 and extend between the opposed pole pieces 120. The rods 130 are formed of nichrome alloy and are copper plated to improve the RF conductivity of the surfaces thereof. As illustrated, the rods 130 are cylindrical in shape and circular in cross section, the diameter of each of the rods 130 being approximately equal to one-half of the dimensions of an associated recess 116, each of the rods 130 being disposed midway between the sidewalls 118 of the associated recesses 116 and being disposed with the outer surface 130a thereof positioned radially outwardly a slight distance from a surface on which would lie the inner surfaces 117 of the anode segments 115, the rods 130 being disposed outwardly a distance of approximately 0.005 inch in a typical construction, whereby each of the rods 130 is essentially disposed within the associated recess 116 and the outer ends thereof extend into and are fixedly secured to the associated pole pieces 120.

The pole pieces 120 arranged adjacent to the opposite ends of the anode 111 are utilized for establishing a unidirectional magnetic field extending axially through the space within the anode 111, and specifically through the interaction space 150 defined between the anode 111 and the cathode 140. To this end a pair of magnet coils 131 and 135 is provided, the magnet coil 131 being disposed about the upper portion of the device 110 as viewed in FIG. 2 and the magnet coil 135 being disposed about the lower portion of the device 110 as viewed in FIG. 2. The coils 131 and 135 are shaped each as a torous, are wound of electrically conductive wire, and as illustrated, are disposed respectively about magnetic yokes 132 and 136 that are in the form of cylinders disposed within the opening in the associated coil, the yokes 132 and 136 in turn having inner openings therein having diameters equal substantially to, or slightly greater than, the external diameter of the outer wall 112 of the anode 111. There further are provided outwardly extending flanges 133 and 137, respectively, on the yokes 132 and 136, the casing 105 being disposed within the flanges 133 and 137 and forming a mechanical connection and a magnetic path therebetween. It will be understood that the pole pieces 120, the magnetic yokes 132 and 136, the flanges 133 and 137, and the casing 105 are all formed of metals having a high magnetic permeability, such as iron and steel, whereby when the magnet coils 131 and 135 are energized, a strong and uniform unidirectional magnetic field is established between the pole pieces 120 within the device 110 and extending axially through the interaction space 150 therein.

The circuit for energizing the coils 131 and 135 can be traced with reference to FIGS. 1 and 2 from the power supply 51, and specifically the DC output terminal 56 thereof, through the conductor 60 to the input terminal 101 of the oscillator 100 to which is connected one terminal of the magnet coil 131. The other terminal of the magnet coil 131 is connected by a conductor 134 to one terminal of the magnet coil 135, and the other terminal of the magnet coil 135 is connected by a conductor 138 to one of the cooling fins 129 by means of a connection 139, whereby the input terminal 101 is connected via the magnet coil 131, the conductor 134, the

magnet coil 135 and the conductor 138 to the anode 111 of the device 110. The flow of current through the magnet coils 131 and 135 serves to produce the unidirectional magnetic field in the interaction space 150 of the crossed-field discharge device 110.

The cathode structure 140 is provided in the axially extending space defined by the anode 111, the cathode structure 140 including a cylindrical wall 141 arranged with the axis thereof disposed at the axis of the anode 111, the wall 141 being formed of a heat-resistant and electrically conducting material, the preferred material of construction being nickel. A first end wall 142 is provided at the upper end of the cathode wall 141 and carries an upwardly extending flange 142a extending therearound, the flange 142a fitting within the associated end of the cathode wall 141 and being suitably secured thereto as by welding. A second end wall 143 is provided at the lower end of the cathode wall 141 and carries a downwardly extending flange 143a extending therearound, the flange 143a fitting within the associated end of the cathode wall 141 and being suitably secured thereto as by welding. The end walls 142 and 143 are also formed of a heat-resistant and electrically conducting material, the preferred material of construction being nickel. The upper end wall 142 has a centrally disposed opening therein which receives therethrough a reduced portion of a conductor 144 formed of copper, the lower end of the conductor 144 being mechanically and electrically secured to the end wall 142, the conductor 144 being generally cylindrical in shape and extending upwardly from the top end wall 142. Disposed about the lower end of the conductor 144 and disposed on the top of and in thermal contact with the end wall 142 is a heat shield 145 that extends outwardly and overlies the associated end of the cathode structure 140, the heat shield being formed of steel.

35 The cathode wall 141 is provided with a sintered porous coating 146 impregnated with a suitable electron emissive oxide material, whereby upon heating of the cathode structure 140, the coating 146 readily emits electrons from the outer surface thereof. Referring particularly to FIG. 6, it will be seen that the coating 146 is shaped to provide a plurality of outward extending projections 147 each having outwardly converging sidewalls joining a generally circumferentially arranged outer surface 148, a space 149 being provided between adjacent projections 147. As illustrated, the circumferential extent of the outer surfaces 148 is substantially equal to the spacing 149 between adjacent projections 147. The preferred range of the circumferential extent of each of the outer surfaces 148 is approximately 25 percent to 60 percent of the circumferential distance between the centers of adjacent outer surfaces 148. The radial dimension of each of the projections 147 is also preferably greater than about 20 percent of the spacing between the anode 111 and the coating 146 on the cathode structure 140. The number of the projections 147 provided on the coating 146 is equal to the sum of the number of the anode segments 115 and the number of the rods 130, whereby there are thirty of the projections 147 provided upon the coating 146. The outer surfaces of the coating 146 together with the inner surfaces of the anode 111 define an interaction space 150 disposed therebetween in which the emitted electrons from the coating 146 interact with the electrical and magnetic fields disposed between the anode 111 and the cathode structure 140. As will be described more fully hereinafter, the projections 147 combine with the anode segments 115 and the rods 130 to provide a preferred distribution of the several fields within the interaction space 150 of the device 110 that results in more desirable operating characteristics of the device 110. One particularly desirable result of the shape of the coating 146 as described is to minimize back heating of the cathode 140, the desirable emitted electrons emanating from the projections 147, and very few undesirable electrons emanating from the spaces 149 between the projections 147, thereby to facilitate emission of desirable electrons and to suppress emission of undesirable electrons.

It further will be noted from FIG. 6 that the center line of each projection 147 is circumferentially displaced relative to the center line of its corresponding anode segment 115 or rod 130, as the case may be; more specifically, the center lines of the projections 147 are displaced in a clockwise direction a circumferential distance equal to approximately 40 percent of the circumferential spacing between the center lines of an adjacent anode segment 115 and an adjacent rod 130. The circumferential displacement of the projections 147 with respect to the corresponding anode segment 115 or rod 130 is preferably in the range between 0 percent and approximately 45 percent of the circumferential spacing between adjacent anode segments and rods, a preferred range being between 25 percent and approximately 45 percent of the spacing between adjacent anode segments and rods, a still more preferred range being between approximately 35 percent and 45 percent of the spacing between adjacent anode segments and rods, and on the downstream side, i.e., in the direction of normal initial electron flow from the projections 147. Finally, it will be noted that the electron emissive coating 146 is confined within the end walls 113 and 114 of the anode 111, the cathode structure 140 being carefully centered with respect to the anode structure 111 and the rods 130.

As illustrated, the cathode structure 140 is of the indirectly heated type, and accordingly, there has been provided within the cathode wall 141 a heater 151 in the form of a coiled filament extending substantially the entire length of the cathode wall 141 and spaced inwardly a short distance from the inner surface thereof. The upper end of the heater 151 as viewed in FIG. 3 has an outer end 152 that extends outwardly into and through an opening in the conductor 144 and outwardly beyond the upper end thereof and is suitably attached as by brazing to a connection 153 formed of copper, the connection 153 being in electrical contact with both the cathode structure 140 and the heater 151. The lower end of the heater 151 has an outer end 154 that is received in and connected to a conductor 155 formed of copper and extending downwardly through an opening in the end wall 143, an insulator 157 formed preferably of ceramic being disposed between the end wall 143 and the conductor 155 to provide electrical insulation therebetween. There further is provided about the conductor 155 a heat shield 156 formed of steel and similar in construction to the heat shield 145 discussed above, the heat shield 156 extending beyond and being in general axial alignment with the lower end of the cathode structure 140. The lower end of the conductor 155 as illustrated is connected to a connector 158 by means of a conductor 159, the connector 158 being in electrical connection with one end of the heater 151 for supplying electrical energy thereto.

The cathode structure 140, the heater 151 and the connected parts are also mechanically mounted upon the pole pieces 120 by means of a pair of annularly shaped insulators 127, the insulators 127 preferably being formed of ceramic to provide a firm structural mount while providing good electrical insulation between the parts. More specifically, each of the insulators 127 is seated in a complementarily shaped recess in the associated pole piece 120, and the upper insulator 127 as viewed in FIG. 3, surrounds the conductor 144 and bears against the upper surface of the heat shield 145, and the lower insulator 147 receives therein a portion of the lower heat shield 156 and is disposed beneath a laterally extending surface thereof, whereby the insulators 127 not only mechanically support but also serve to electrically insulate this end of the cathode structure 140 with respect to the associated pole piece 120.

A pair of identical end structures 160 is provided at opposite ends of the device 110 and serve to provide mechanical support for the anode structure 111, the pole pieces 120, the rods 130 and the cathode structure 140 with respect to each other and hermetically to seal the space within the device 110. Since the end structures 160 are identical in construction, only one will be described in detail, like reference numerals being applied to like parts of the end structure 160. A first seal

member 161 is provided formed of a good electrical conducting material that is nonmagnetic, the preferred material being "Fernico" alloy, a typical composition being 54 percent iron, 28 percent nickel and 18 percent cobalt. The seal member 161 is generally conical in shape and converges outwardly with respect to the associated end of the anode 111, an out-turned flange 162 being provided on the larger end thereof and adapted to rest upon the associated end wall 113 or 114 of the anode 111, and to be secured thereto such as by brazing to provide a good electrical connection and a good mechanical connection and a hermetic seal therewith. An inturned flange 163 is provided at the outer or smaller end of the seal member 161, the flange 163 extending inwardly and overlying the annular projection 122 on the associated pole piece 120, an insulating disc 164 being provided therebetween, the disc 164 being preferably of a good electrical insulating material, the preferred material being a ceramic. A like annular insulating disc 165 is disposed upon the outer surfaces of the flange 163, the disc 165 likewise being formed of ceramic and surrounding the associated pole piece 120 and spaced slightly outwardly with respect thereto. A second seal member 166 is provided about the outer end of the associated pole piece 120, the seal member 166 also being formed of a material having good electrical conductivity and being nonmagnetic, the preferred material being "Fernico" alloy. The seal member 166 is preferably cylindrical in shape and embraces and extends around the associated pole piece 120 and is electrically connected thereto to provide an electrical connector therefor and for the rods 130 connected thereto. An out-turned flange 167 is provided on the inner end of the seal member 166, the flange 167 overlying the outer surface of the insulating disc 165 and having a flange 168 integral with the outer edge thereof and surrounding and embracing the outer wall of the associated disc 165. An inturned flange 169 is formed integral with the other end of the seal member 166, the flange 169 overlying the outer end of the associated pole pieces 120. Another seal member 170 is provided formed of a material such as a "Fernico" alloy that is particularly adapted for sealing both to a ceramic surface and to a metal surface, is electrically conductive and nonmagnetic. The seal member 170 more specifically includes an out-turned flange 171 that overlies the flange 169 and is suitably secured thereto as by brazing to provide electrical connection therewith and to form an hermetic seal therewith. An inturned flange 172 is provided on the outer end of the seal member 170 and makes sealing contact with an insulating sleeve 173 that surrounds the associated output conductor 144 or 155, as the case may be, the outer end of the insulating sleeve 173 having an inturned flange 174 having an opening centrally thereof that receives the inner end of the associated connector 153 or 158, as the case may be. Preferably the insulating sleeve 173 is formed of ceramic. Finally, a seal member 175 is provided formed of a material that is particularly adapted for sealing both to a ceramic surface and to a metal surface, is electrically conductive and nonmagnetic, the preferred material being a copper alloy. The seal member 175 is generally cylindrical in shape and surrounds the outer ends of the insulating sleeve 173 and is hermetically sealed thereto. The outer end of the seal member 175 carries an integral inturned flange 176 that is suitably secured as by brazing to the associated connector 153 or 158, as the case may be, to provide good electrical connection therewith and to provide a hermetic seal therebetween.

It will be understood that the end structures 160 each hermetically seals the associated end of the device 110 and also provides electrical connections between parts where desired, while providing electrical insulation between other parts where necessary. Further, it is often desirable to provide gaskets or other like constructions between contacting surfaces when formed of different materials, all as is well understood in the art.

Referring again to FIG. 2 of the drawings, the manner in which the crossed-field discharge device 110 is incorporated

in the oscillator 100 will be described in further detail. A tubular conductor 107 is provided formed of a material that is electrically conductive, the preferred material being aluminum metal; the conductor 107 has an internal diameter slightly greater than the external diameter of the anode 111 and is placed in telescoping relationship with the upper end thereof and is electrically connected thereto, the conductor 107 being disposed within the upper magnetic yoke 132 and extending upwardly to the upper end thereof. Disposed within the tubular conductor 107 is a tubular conductor 82 also formed of aluminum and arranged concentrically with respect to the tubular conductor 107, the lower end of the conductor 82 terminating above the lower end of the tubular conductor 107 and the upper end of the conductor 82 extending upwardly beyond the upper end thereof. The outer conductor 65 of the transmission line 64 has a bottom wall 65a having an opening therein surrounded by a dependent flange 65c, the upper end of the tubular conductor 82 extending upwardly within the flange 65c and being mechanically and electrically connected thereto as by brazing.

As is illustrated in FIG. 3, the connector 153 at the upper end of the crossed-field discharge device 110 has the outer external surface thereof threaded and extends into a complementarily threaded opening in the lower end of the terminal 102, whereby a good electrical connection is provided between the connector 153 and the terminal 102, the terminal 102 extending upwardly through the transmission line 64 and outwardly through an opening in the upper wall 65b of the outer conductor 65. A coupler and filter assembly 83 is provided for the terminal 102 so that the B- potential and the AC heater potential can be applied thereto via the conductor 61 and RF potentials can be taken therefrom and applied to the transmission line 64 without any leakage of the RF potentials into the power supply 51 via the conductor 61. The coupler and filter assembly 83 includes an insulating dielectric sleeve 84 that surrounds the upper portion of the terminal 102, the sleeve 84 extending from approximately the bottom wall 65a of the outer conductor 65 upwardly past the upper wall 65b of the outer conductor 65; the sleeve 84 is preferably formed of a synthetic organic resin, the preferred resin being a tetrafluoroethylene resin sold under the trademark "Teflon." Surrounding the insulating sleeve 84 is a conductive sleeve 85 that is formed of a material having good electrical conductive properties, the preferred material being aluminum metal. The lower end of the conductive sleeve 85 is spaced upwardly a short distance from the lower end of the insulating sleeve 84 and extends upwardly beyond the top wall 65b of the outer conductor 65 and has an out-turned flange 86 that rests upon the upper surface of the top wall 65b. Disposed about the conductive sleeve 85 and immediately below the lower surface of the top wall 65b is an insulating block 63 also preferably formed of a synthetic organic plastic resin, the preferred resin being a tetrafluoroethylene resin sold under the trademark "Teflon." The insulating block 63 is generally cylindrical in shape and closely fits about the conductive sleeve 85 and extends from the lower surface of the top wall 65b downwardly to the upper surface of the inner conductor 66. Disposed below the inner conductor 66 and engaging the outer surface of the conductive sleeve 85 is a locking nut 69 which presses the inner conductor 66 against the lower end of the insulating block 63 which in turn presses the top wall 65b against the under surface of the out-turned flange 86, whereby to clamp all of the parts in the positions illustrated. An insulating washer 87, preferably formed of mica, overlies the flange 86 and receives the upper end of the insulating sleeve 84 in an opening therethrough. Disposed on top of the insulating washer 87 is a conductive washer 88, preferably formed of copper, to which electrical connection is made for the conductor 61. Finally, the outer end of the terminal 102 is threaded as at 102a and carries a nut 89, preferably formed of steel, which serves to clamp the washers 87 and 88 against the out-turned flange 86.

At the lower end of the crossed-field discharge device 110, a tubular conductor 108 is provided formed of a material that is electrically conductive, the preferred material being aluminum metal; and the conductor 108 has an internal diameter slightly greater than the external diameter of the anode 111 and is placed in telescoping relationship with the lower end thereof and is electrically connected thereto, the conductor 108 being disposed within the lower magnetic yoke 136 and extending downwardly to the lower end thereof. Disposed within the conductor 108 is an insulating sleeve 108a, and there is disposed within the insulating sleeve 108a an annular metallic conductor 184 that extends downwardly and slightly beyond the lower magnetic yoke 136. The lower end of the conductor 184 is closed by a cover 109 also formed of a material that is electrically conductive, the preferred material being aluminum; the cover 109 is generally circular in outline and has an upturned flange 109a thereon that surrounds the lower end of the conductor 184, the conductor 184 and the cover 109 being suitably joined as by welding.

As illustrated in FIG. 3, the connector 158 at the lower end of the crossed-field discharge device 110 has the outer external surfaces thereof threaded and extends into a complementarily threaded opening in the upper end of the terminal 103, whereby a good electrical connection is provided between the connector 158 and the terminal 103, the terminal 103 extending downwardly through an opening in the center of the cover 109 and outwardly therewith. A coupler and filter assembly 90 is provided for the terminal 103 so that the AC heater potential can be applied thereto via the conductor 62, and RF potentials associated with the crossed-field discharge device 110 and also appearing on the upper end of the terminal 103 will be filtered out so as positively to prevent introduction thereof into the power supply 51 via the conductor 62. The coupler and filter assembly 90 includes an insulating dielectric sleeve 91 that surrounds the lower portion of the terminal 103, the sleeve 91 extending from a point below the cover 109 and upwardly well toward the seal member 175; the sleeve 91 is preferably formed of a synthetic organic resin, the preferred resin being a tetrafluoroethylene resin sold under the trademark "Teflon." Surrounding the insulating sleeve 91 is a conductive sleeve 92 that is formed of a material having good electrical conductive properties, the preferred material being aluminum metal. The upper end of the conductive sleeve 92 is spaced downwardly a short distance from the upper end of the insulating sleeve 91 and extends downwardly beyond the cover 109 and has an out-turned flange 93 that rests upon the lower surface of the cover 109. An insulating washer 94, preferably formed of mica, underlies the flange 93 and receives the lower end of the insulating sleeve 91 in an opening therethrough. Disposed below the insulating washer 94 is a conductive washer 95, preferably formed of copper, to which electrical connection is made for the conductor 62. Finally, the outer end of the terminal 103 is threaded as at 103a and carries a nut 96, preferably formed of steel, which serves to clamp the washers 94 and 95 against the out-turned flange 93 which is in turn clamped against the underside of the cover 109, there thus being formed a good electrical connection between the flange 93 and the cover 109.

During the operation of the crossed-field discharge device 110, the anode 111 and the rods 130 cooperate to provide a portion of a coaxial transmission line within the device 110, the coaxial transmission line thus formed accommodating axially extending RF waves therein. The anode 111 and the cathode structure 140 also cooperate to provide a portion of another coaxial transmission line that also accommodates axially extending RF waves therein. Further, the rods 130 and the cathode structure 140 cooperate to provide a portion of yet another coaxial transmission line for accommodating axially extending RF waves therein.

As a consequence of this fundamental characteristic of the crossed-field discharge device 110, the oscillator 100 can be formed by connecting a section of coaxial transmission line 75 between the anode 111 and the rods 130, for example, and

shorting the coaxial transmission line at a point to provide a cavity or tuned circuit 180 that is resonant at the desired operating frequency. Such a connection is illustrated in FIG. 2 of the drawings, wherein the tubular conductor 82 serves as the outer conductor of a coaxial transmission line for a tuned circuit 180, the conductor 82 being coupled to the anode 111. An inner conductor 182 is provided in the form of an annular conductor having the lower end thereof disposed about and in electrical connection with the associated seal member 166 which is electrically connected to the rods 130 through the associated pole piece 120. As a consequence, the concentric conductors 82 and 182 form a section of a coaxial transmission line that is connected to one end of the coaxial transmission line within the device 110 formed by the anode 111 and the rods 130. To form a tuned resonant cavity, it is necessary only to provide an RF short between the concentric conductors 82 and 182 at a point spaced a predetermined distance from a plane normal to the axis of the anode 111 disposed midway between the end walls 113 and 114 thereof, the predetermined distance being equivalent to one-fourth of the wavelength of the desired frequency of operation of the oscillator 100. As illustrated in FIG. 2, such an RF short is provided by a cylinder 183 disposed between the outer end of the conductor 182 and the cooperating conductor 82, the cylinder 183 providing an RF short between the concentric conductors 82 and 182; to this end the cylinder 183 is formed of a material having a high magnetic permeability so as to improve the shape and uniformity of the magnetic fields in the device 110, the preferred material for forming the cylinder 183 being a magnetically permeable steel having copper plating thereon to improve the conductivity thereof with respect to RF energy.

Recapitulating, the tuned circuit 180, which comprises a part of the resonant circuit of the oscillator 100, is formed by an outer conductor extending from the longitudinal midplane of the device 110 and comprising the inner surfaces of the anode 111 and the conductor 82 connected thereto, and an inner conductor extending from the longitudinal midplane of the device 110 and comprising the outer surfaces of the rods 130 and the conductor 182 connected thereto, the outer ends of the conductors 82 and 182 being shorted by the cylinder 183, the distance from the midplane of the device 110 to the inner surface of the cylinder 183 being equivalent to one-fourth of the wavelength of the desired frequency of operation of the oscillator 100.

A like tuned circuit 185 having a length equal to one-fourth of the wavelength of the desired frequency of operation of the oscillator 100 is provided between the anode 111 and the rods 130 at the lower end of the device 110 as viewed in FIG. 2. The tuned circuit 185 is in the form of a section of a coaxial transmission line having one end connected between the anode 111 and the rods 130, the tubular conductor 184 serving as the outer conductor of the coaxial transmission line for the tuned circuit, the conductor 184 being capacitively coupled to the anode 111. An inner annular conductor 188 is provided having the upper end thereof disposed about and in electrical connection with the associated seal member 166 which is electrically connected to the rods 130 through the associated pole piece 120. As a consequence, the concentric conductors 184 and 188 from a section of a coaxial transmission line that is connected to one end of the coaxial transmission line formed by the anode 111 and the rods 130. To form a tuned resonant cavity at the lower end of the device 110, it is necessary only to provide an RF short between the concentric conductors 184 and 188 at a point spaced a predetermined distance from a plane normal to the axis of the anode 111 midway between the end walls 113 and 114 thereof, the predetermined distance being equivalent to one-fourth of the wavelength of the desired frequency of operation of the oscillator 100. As illustrated in FIG. 2, such an RF short is provided by a cylinder 189 disposed between the outer end of the conductor 188 and the cooperating conductor 184, the cylinder 189 providing an RF short between the concentric conductors 184 and 188; to this end the cylinder 189 is

formed of a material having a high magnetic permeability so as to improve the shape and uniformity of the magnetic fields in the device 110, the preferred material for forming the cylinder 189 being a magnetically permeable steel having a copper plating thereon to improve the conductivity thereof with respect to RF energy.

Recapitulating, the tuned circuit 185, which comprises a part of the resonant circuit of the oscillator 100, is formed by an outer conductor extending from the longitudinal midplane of the device 110 and comprising the inner surfaces of the anode 111 and the conductor 184 connected thereto, and an inner conductor extending from the longitudinal midplane of the device 110 and comprising the outer surfaces of the rods 130 and the conductor 188 connected thereto, the outer ends of the conductors 184 and 188 being shorted by the cylinder 189, the distance from the midplane of the device 110 to the inner surface of the cylinder 189 being equivalent to one-fourth of the wavelength of the desired frequency of operation of the oscillator 100.

In the operation of the oscillator 100, it is necessary to produce within the crossed-field discharge device 110 a predetermined pattern of electrical and magnetic fields. A description of the electrical and magnetic fields within the device 110 during the operation thereof as an oscillator connected as illustrated in FIG. 2 will be given. The operating potentials for the device 110 are derived from the power supply 51 described above, and more particularly, the heater supply is provided from the power supply output terminals 54 and 55, the terminal 54 being connected by the conductor 62 to the terminal 103 (see FIG. 2 also), and the terminal 55 being connected by the conductor 61 to the terminal 102. The DC potential from the power supply 51 is derived specifically from the output terminals 56 and 57 thereof, a conductor 60 interconnecting the output terminal 56 of the power supply 51 to the input terminal 101 (see FIG. 2 also) which is connected via the magnet coil 131, the conductor 134, the magnet coil 135, the conductor 138, and a fin 129 to the anode 111 to apply B+ potential thereto, and a conductor 61 interconnecting the output terminal 57 of the power supply 51 to the terminal 102 to apply B- operating potential thereto and to the cathode 140 that is connected thereto via the conductors 144 and 152 and the connector 153.

The application of the above described B+ and B- potentials to the anode 111 and the cathode 140, respectively, establishes a unidirectional electrical field 191 (see FIG. 8) that extends between the anode segments 115 and the cathode projections 147 and also between the rods 130 and the cathode projections 147; it will be noted that an adjacent pair of the cathode projections 147 provides a unidirectional electrical field in cooperation with a single associated anode segment 115 and a single associated rod 130. The electrical field 191 extends substantially normal to the longitudinal axis of the anode 111, the field lines entering the surfaces 117 and 130a normal thereto and entering the surfaces 148 normal thereto, whereby the field 191 takes the shape illustrated in FIG. 8.

In order to provide the necessary unidirectional magnetic field normal to or "crossed" with respect to the field 191, a DC current is established in the magnet coils 131 and 135. More particularly, electrons flow from the anode 111 through the conductor 138, the magnet coil 135, the conductor 134, the magnet coil 131 and the conductor 60 to the power supply output terminal 56. When such a flow of electrons is established through the magnet coils 131 and 135, a strong unidirectional magnetic flux is established through the upper flange 133, the magnetic yoke 132, the upper pole piece 120 (see FIG. 3 also), through the interaction space 150, through the lower pole piece 120, the magnetic yoke 136 and the flange 137. A return path for the unidirectional magnetic field is provided through the casing 105 which is formed of a material that is magnetically permeable. In passing it is noted that the RF shorts 183 and 189 are also magnetically permeable and cooperate in establishing the unidirectional magnetic field through the interaction space 150.

Referring to FIG. 10 of the drawings, the unidirectional magnetic flux lines extending through the interaction space 150 are designated by the numeral 193, the flux lines 193 extending axially through the interaction space 150 and therefore normal to the plane of the sheet of drawing in FIG. 10. Due to the provision of the pole pieces 120, and the other portions of the magnetic path having high magnetic permeability described above, there is a uniform distribution of the unidirectional flux lines 193 throughout the recesses 116, about the rods 130 and inwardly to the outer surface of the electron emissive coating 146. It further is pointed out that the unidirectional magnetic flux lines 193 are disposed normal to the unidirectional electrical field 191 illustrated in FIG. 8, whereby the unidirectional electrical field 191 and the unidirectional magnetic field 193 provide the necessary "crossed" fields for the operation of the crossed-field discharge device 110.

As has been pointed out above, the anode 111 and the rods 130 cooperate to provide a coaxial transmission line that extends axially with respect to the device 110 and that is open at both ends within the device 110. In the oscillator 100, the open ended transmission line thus provided by the anode 111 and the rods 130 has connected to the upper end thereof an external coaxial transmission line comprised of the concentric conductors 82 and 182, the conductors 82 and 182 being shorted by the RF short 183 to provide a tuned resonant cavity 180 that is a part of the resonant circuit for the oscillator 100. The open ended transmission line thus provided by the anode 111 and the rods 130 has connected to the lower end thereof an external coaxial transmission line comprised of the concentric conductors 184 and 188, the conductors 184 and 188 being shorted by the RF short 189 to provide a tuned resonant cavity 185 that is a part of the resonant circuit for the oscillator 100. More specifically, the tuned circuit for the oscillator 100 is the cavity that extends between the RF shorts 183 and 189 including the tuned circuit 180 and the tuned circuit 185 and the space between the anode 111 and the rods 130 within the device 110. When the tuned resonant circuit thus formed is excited by the establishment of the unidirectional electrical field 191 of FIG. 8 and the unidirectional magnetic field of FIG. 10, the tuned cavity resonates at a frequency having a wavelength equal to twice the distance between the facing surfaces of the RF shorts 183 and 189, i.e., a standing RF wave is established within the tuned cavity and extends axially thereof and axially of the device 110 and through the interaction space 150 thereof.

There is believed to be associated with the standing RF wave thus established an RF electrical field disposed normal to the axis of the device 110, a diagrammatic representation of the field being illustrated in FIG. 7. From FIG. 7, it will be seen that at any moment, the anode segments 115 have one RF polarity while the rods 130 have the opposite RF polarity, whereby there is a relatively strong RF field between the anode 111 and the rods 130 as well as RF fields between the cathode 140 and the anode 111 and between the cathode 140 and the rods 130. In FIG. 7, the instantaneous RF electrical field has been designated by the numeral 190, and the portion thereof disposed between the anode 111 and the rods 130 has been designated 190a, the force lines being disposed normal to the surfaces associated therewith, i.e., normal to the sidewalls 118 and the outer wall 119 of the recesses 116 and the surfaces of the rods 130. There is a weaker RF electrical field between the anode 111 and the cathode 140, that field being designated by the numeral 190b, the lines representing the field 190b being normal to the inner surfaces 117 of the anode segments 115 and normal to the outer surfaces 148 of the cathode projections 147. Finally, there is a still weaker RF electrical field between the rods 130 and the cathode 140, that field being designated 190c, the lines representing the field 190c also being disposed normal to the associated surfaces, and specifically normal to the outer surfaces of the rods 130 and normal to the outer surfaces 148 of the associated cathode projections 147.

Associated with the RF electrical field 190 of the standing RF wave is an RF magnetic field 192 which is believed to have the form illustrated in FIG. 9; the magnetic field 192 is also disposed normal to the axis of the device 110 and is concentrated about and surrounds the rods 130. The major portion of the RF magnetic field 192 is disposed within the anode recesses 116, but a portion of the magnetic field 192 extends inwardly into the interaction space 150 and is coupled to the cathode 140.

- 5 10 After the application of the operating potentials to the device 110, and after the cathode 140 has been heated to the operating temperature thereof by the heater 151, electrons are emitted from the emissive coating 146, the electrons being emitted into the interaction space 150 where they are subjected to the action of the unidirectional fields and the RF fields described hereinabove. There is illustrated in FIG. 11 of the drawings a diagrammatic representation of typical paths of electrons emitted from the cathode projections 147, the electron paths being designated by the numeral 194. As illustrated, the electrons follow a spiral path in which the initial direction of flow is in a clockwise direction, this being due to the influence of the unidirectional magnetic field 193 described above. Eventually, the spiral paths 194 of the electrons carry them into contact with the anode 111 or the rods 130, whereby to complete an electrical circuit through the device 110. During the time that the electrons are in the spiral paths 194, they impart a portion of the energy content thereof to the RF standing wave within the device 110 to add power thereto and reinforce the RF standing wave.

15 20 There is illustrated in FIG. 12 a composite representation of all of the fields that are believed to be present in the device 110 and in the interaction space 150 thereof when the device 110 is a part of the oscillator 100. From FIG. 12 it is apparent that the electrons in the paths 194 clearly interact with the unidirectional fields and the RF fields within the interaction space 150, whereby to give up a portion of the energy of the electrons to the RF fields within the interaction space 150. In this manner the RF standing wave within the device 110 and the tuned circuits 180 and 185 associated therewith is maintained and the energy content thereof increased and replenished during the operation of the oscillator 100.

25 30 35 40 45 50 55 60 65 70 75 As is best seen from FIGS. 2, 3 and 12, the cathode 140 is coupled to the RF standing wave within the interaction space 150 and therefore serves as a probe for the removal of a portion of the RF energy from the tuned cavity for supplying thereof to the output transmission line 64. The output from the device 110 and the oscillator 100 appears as an RF potential between the anode 111 and the cathode 140, the anode 111 being coupled to the outer conductor 65 of the output transmission line 64. The conductive sleeve 85 has a length equivalent to one-fourth of the wavelength of the operating frequency of the oscillator 100, and has the flange 86 thereof in electrical contact with the outer conductor 65. The dielectric insulating sleeve 84 couples the output terminal 102 connected to the cathode 140 to the conductive sleeve 85, whereby the RF potential between the anode 111 and the cathode 140 is coupled across the conductive sleeve 85, the maximum RF potential being at the lower end of the conductive sleeve 85 and the minimum RF potential being at the upper end thereof. A portion of the RF potential developed along the conductive sleeve 85 is coupled therefrom by the connection of the inner conductor 66 to an intermediate point therealong, whereby to provide an RF potential between the outer conductor 65 and the inner conductor 66 of the output transmission line 64. The described connection can be considered as an autotransformer wherein the outer conductor 65 is connected to one end of the transformer, the cathode terminal 102 is capacitively coupled to the other end of the transformer and the inner conductor 66 is connected to an intermediate point on the transformer.

The coupler and filter assembly 83 further serves to filter from the conductor 61 the RF energy derived from the oscillator 100. The filter comprises the conductive sleeve 85 which

in cooperation with the terminal 102 and the insulating sleeve 84 forms a low impedance transmission line. The terminal 102 also forms with the outer conductor 82 a high impedance transmission line. At the junction at the lower end of the conductive sleeve 85, there is a substantial mismatch of the high impedance transmission line and the low impedance transmission line resulting in a large reflection of RF energy attempting to flow in the low impedance transmission line formed by the cathode terminal 102 and the conductive sleeve 85. The washer 88 in cooperation with the outer conductor 65 can be considered to be another transmission line of high impedance at the junction therebetween such that a substantial mismatch with the transmission line comprised of the cathode terminal 102 and the conductive sleeve 85 which has a relatively low impedance, and consequently there is a large reflection of RF energy back into the oscillator 100 and away from the conductor 61. When the transmission line including the cathode terminal 102 and the conductive sleeve 85 with the insulating sleeve 84 therebetween is made to have a length equivalent to one-fourth of the wavelength of the frequency of operation of the oscillator 100, maximum attenuation is attained, RF energy within the oscillator 100 flowing from the terminal 102 to the conductive sleeve 85, through the outer conductor 65 and back to the device 110. Substantially no RF energy then flows through the line including the terminal 102 and the conductive sleeve 85 and to the washer 88 and the attached conductor 61.

The coupler and filter assembly 90 operates in a manner like the coupler and filter assembly 83, the construction and theory of operation being the same, and accordingly, a detailed description thereof will not be given in the interest of brevity, it merely being pointed out that the conductive sleeve 92 has a length equivalent to one-fourth of the wavelength of the frequency of operation of the oscillator 100 and the cover 109 performs the same function as the outer conductor 65 in the operation of the coupler and filter assembly 83.

As has been explained above, the RF wave present within the oscillator 100 extends axially with respect to the device 110, there being no radial RF waves within the device 110, i.e., no RF waves extending normal to the axis of the device 110. Furthermore, the radial distance between the outer surface of the cathode 140 and the outer wall 119 of the anode recesses 116 is less than that required to accommodate a radial standing wave at the operating frequency of the oscillator 100. In fact, the radial distance between the outer surface of the cathode 140 and the outer walls 119 of the anode recesses 116 is less than that required to accommodate a radial standing wave at an operating frequency having a wavelength corresponding to twice the distance between the ends of the anode 111, whereby there could be no radial RF standing wave even if it were possible to short the transmission line formed by the anode 111 and the rods 130 at the end walls 113 and 114.

There is illustrated in FIG. 13 a modified oscillator circuit 100A incorporating therein the crossed-field discharge device 110 having associated therewith the magnet coils 131 and 135 and provided at the upper end thereof with the coupler and filter assembly 83 and at the lower end thereof with the coupler and filter assembly 90 described above. In the oscillator circuit 100A, a tuned resonant circuit having a length equal to one-fourth of the wavelength of the operating frequency has been provided rather than a tuned resonant circuit having a length equal to one-half of the wavelength of the operating frequency of the oscillator as in FIG. 2 of the drawings; in other words, the difference between the oscillator circuit 100 of FIG. 2 and the oscillator circuit 100A of FIG. 13 resides in the construction and operation of the tuned circuits coupled to the device 110, and more particularly between the anode 111 and the rods 130 thereof. Accordingly, like reference numerals from FIG. 2 have been applied to like parts in FIG. 13, and parts in FIG. 13 that are similar in construction and function to parts in FIG. 2 have been given the same reference numeral but with the addition of a suffix A thereto.

The upper end of the anode 111 has connected thereto and extending upwardly therefrom the tubular conductor 107A, the conductor 107A terminating at the upper end of the magnetic yoke 132. The upper end of the tubular conductor 82 extends beyond the upper end of the magnetic yoke 132 and is received within the dependent flange 65a on the transmission line bottom wall 65a, the upper end of the conductor 82 being fixedly secured to and electrically connected to the flange 65c. A tuned resonant circuit 180A is connected between the anode 111 and the rods 130, and more specifically includes the tubular conductor 82 described above that is coupled to the anode 111 and an inner coaxial conductor 182A that is electrically connected to the seal member 166 that is in turn electrically connected to the rods 130. The outer ends of the concentric conductors 82 and 182A are shorted by an RF short 183A that is also preferably magnetically permeable, whereby the RF short 183A is formed preferably of a magnetically permeable steel that is copper plated to provide good RF conductivity on the outer surface thereof. The distance between the lower surface of the RF short 183A and the end wall 114 of the anode 111 is equal to one-fourth of the wavelength of the operating frequency of the oscillator 100A. The other end of the transmission line formed by the anode 111 and the rods 130 is open, whereby the frequency of operation of the oscillator 100A is determined by the resonant frequency of the tuned cavity 180A. The lower end of the tube 13 is terminated by the coupler and filter assembly 90. More specifically, the tubular conductor 108 is mounted on and electrically connected to the lower end of the anode 111 and extends downwardly well below the lower end of the magnetic yoke 136. The conductor 108 together with the metallic cover 109 closing the end thereof serves to prevent escape of RF energy from the lower end of the device 110.

The coupler and filter assembly 83 at the upper end of the oscillator 100A serves to couple the RF energy appearing between the conductor 82 and the output terminal 102, to the transmission line 64 and specifically between the outer conductor 65 and the inner conductor 66 thereof. The coupler and filter assembly 83 further permits the connection of the DC B- voltage and the AC heater voltage on the conductor 61 to the output terminal 102 without permitting escape of the RF energy from the oscillator 100A along the conductor 61, all as has been described above. Similarly, the coupler and filter assembly 93 at the lower end of the oscillator 100A permits the AC heater potential on the conductor 62 to be applied to the terminal 103 without permitting the escape of RF energy from the oscillator 100A along the conductor 62.

The various unidirectional electrical and magnetic fields and the various RF electrical and magnetic fields present in the oscillator 100A of FIG. 13 are substantially the same as those in the oscillator circuit 100 illustrated in FIG. 2, whereby the fields present in the device 110 incorporated in the oscillator circuit 100A during the operation thereof are believed to be the same as those illustrated in FIGS. 7 to 12 that have been described above.

The frequency of operation of the oscillator circuit is dependent upon the length of the connected tuned resonant cavity, i.e., in a one-half wavelength-tuned resonant cavity the frequency is a function of the distance between the RF shorts at the ends of the coaxial transmission lines forming the resonant cavity. In other words, changing the distance between the RF shorts at the ends of the coaxial transmission lines connected to the device 110 between the anode 111 and the rods 130 thereof serves to change and adjust the frequency operation of the oscillator circuit. There is illustrated in FIG. 14 of the drawings an oscillator circuit 100B in which structure is provided for tuning the resonant circuit connected to the device 110. As illustrated, there is connected to the upper end of the device 180 a first-tuned circuit 180B comprising a section of a coaxial transmission line including an outer conductor 82 and an inner conductor 182B, the outer conductor 82

being coupled to the concentric tubular conductor 107 that is directly connected to the anode 111, and the inner conductor 182B being directly connected to the seal member 166 that is in turn in direct connection with the rods 130. An RF short 183B is provided at the outer end of the coaxial transmission line, thereby to complete the tuned circuit 180B. Preferably, the distance between the midpoint of the device 110 and the adjacent surface of the RF short 183B is equal to approximately one-fourth of the wavelength of the operating frequency of the oscillator 100B.

Connected to the other end of the device 110 and disposed at the bottom of FIG. 14 is a second tuned circuit 185B comprising a section of a coaxial transmission line including an outer conductor 108 and an inner conductor 188B. The outer conductor 108 is directly connected to the anode 111, and the inner conductor 188B is directly connected to the adjacent seal member 166 that is in turn directly connected to the adjacent ends of the rods 130. The coaxial transmission line comprising the conductors 108 and 188B is terminated by an RF short 189B extending therebetween and having an annular insulator 184B disposed therein and making sliding contact with the adjacent walls of the concentric tubular conductors. Structure further is provided to adjust the position of the RF short 189B along the coaxial transmission line, that structure including a rod 186B having the upper end thereof threadedly connected to the RF short 189B and carrying on the other end thereof a knurled handle 187B. By means of the handle 187B, the position of the RF short 189B can be adjusted, thereby to adjust the effective electrical length of the tuned circuit 185B, and thus to change the distance between the adjacent faces of the two RF shorts 183B and 189B, thus to change the resonant frequency of the tuned circuit in the oscillator 100B.

Recapitulating, the tuned circuits 180B and 185B, which comprise the resonant circuit of the oscillator 100B, are each formed by an inner conductor and an outer conductor, the conductors of the tuned circuit 180B extending outwardly in one direction from the longitudinal midplane of the device 110 and being connected together at the outer ends thereof by an RF short 183B, and the conductors of the tuned circuit 185B extending outwardly in the opposite direction from the longitudinal midplane of the device 110 and being connected together at the outer ends thereof by an RF short 189B, the total distance from the RF short 183B to the RF short 189B being equivalent to one-half of the wavelength of the desired frequency of operation of the oscillator 100B.

An oscillator can also be formed by connecting a section of coaxial transmission lines between the anode 111 and the cathode 140 and shorting the coaxial transmission lines at a point to provide a cavity that is resonant at the desired operating frequency. Such a connection is illustrated in FIG. 15 of the drawings, wherein an oscillator 200 is illustrated incorporating therein the device 110 connected as an oscillator and supplying microwave energy to the output transmission line 64. The oscillator 200 includes a first resonant cavity 280 connected to the upper end of the device 110 and including an outer conductor 82 and an inner conductor 282 that cooperate to form a coaxial transmission line. The conductor 82 is capacitively coupled by the coupler 80 to the anode 111, and the inner conductor 282 is capacitively coupled to the cathode 140 through the terminal 102 that is in electrical connection therewith. To form the tuned resonant cavity 280, an RF short 283 is provided between the concentric conductors 82 and 282 at a point spaced a predetermined distance from a plane normal to the axis of the anode 111 midway between the end walls 113 and 114 thereof, the predetermined distance being equivalent to one-fourth of the wavelength of the desired frequency of operation of the oscillator 100.

Another tuned circuit 285 is provided at the other end of the device 110 and is in the form of a coaxial transmission line including an outer conductor 108 and an inner conductor 288. The outer conductor 108 is directly connected to the anode 111 at the adjacent ends thereof, and the inner conductor 288 is capacitively coupled to the adjacent end of the cathode 140

through the conductor 103. An RF short 289 is provided at the lower end of the coaxial conductors 108 and 288 to complete the tuned circuit 285. Preferably the inner surface of the RF short 289 is disposed from the midpoint of the device

110 a distance equivalent to one-fourth of the wavelength of the desired frequency of operation of the oscillator 100. The tuned circuits 280 and 285 cooperate with the device 110 to form a continuous tuned cavity having a length equal to one-half of the wavelength of the frequency of operation of the oscillator 200.

Recapitulating, the tuned circuits 280 and 285, which comprise the resonant circuit of the oscillator 200, are each formed by an inner conductor and an outer conductor, the conductors of the tuned circuit 280 extending outwardly in one direction from the longitudinal midplane of the device 110 and being connected together at the outer ends thereof by an RF short 283, and the conductors of the tuned circuit 285 extending outwardly in the opposite direction from the longitudinal midplane of the device 110 and being connected together at the outer ends thereof by an RF short 289, the distances from the midplane of the device 110 to the RF shorts 283 and 289 each being equivalent to one-fourth of the wavelength of the desired frequency of operation of the oscillator 200.

In order to provide an electrical connection to the rods 130, a shorting terminal 295 is provided, the shorting terminal 295 including an annular body portion 296 surrounding the associated seal member 166 that is directly connected to one end of the rods 130, and also includes a spring arm 297 that is in good electrical contact with the tubular conductor 107 that is in direct connection with the anode 111. Accordingly, the anode 111 and the rods 130 will be maintained at substantially the same potential during the operation of the oscillator 200.

Upon the establishment of the unidirectional electrical and magnetic fields in the device 110, the tuned cavity including the tuned circuits 280 and 285 in the oscillator 200 resonates at a frequency having a wavelength equal to twice the distance between the inner surfaces of the RF shorts 283 and 289, i.e., a standing RF wave is established within the tuned cavity and extends axially thereof and axially of the device 110 and through the interaction space thereof. It is believed that there is associated with the standing RF wave thus established an RF electrical field disposed normal to the axis of the device 110, a diagrammatic representation of the field being illustrated in FIG. 16. From FIG. 16, it will be seen that at any moment, the anode segments 115 and the rods 130 connected directly thereto have one RF polarity while the cathode 140 has an opposite RF polarity. Accordingly, there is a relatively strong RF field between the anode 111 and the cathode 140 and also between the rods 130 and the cathode 140, and a relatively weak RF field between the anode 111 and the rods 130. In FIG. 16, the instantaneous RF electrical field has been designated by the numeral 290, and the portion thereof disposed between the anode 111 and the cathode 140 has been designated 290b, the force lines being disposed normal to the surfaces associated therewith, i.e., normal to the outer surfaces 117 and normal to the outer surfaces 148. There is a slightly weaker RF field between the rods 130 and the cathode 140, that field being designated by the numeral 290c, the force lines representing the field 290c being normal to the surfaces of the rods 130 and the outer surfaces 148. Finally, there is a much weaker RF electrical field between the anode 111 and the rods 130, that field being designated 290a, the force lines representing the field 290a also being disposed normal to the associated surfaces, and specifically normal to the outer surfaces of the rods 130 and normal to the surfaces of the recess 116.

It is believed that there is associated with the RF electrical field 290 of the standing RF wave in the oscillator 200 an RF magnetic field 292 which is illustrated in FIG. 17. The magnetic field 292 is also disposed normal to the axis of the device 110 and to the electrical field 290 and includes a first field 292a surrounding the rods 130 and a second and stronger field

292b surrounding the cathode 140 and disposed in the interaction space 150. In fact, the major portion of the RF magnetic field 292 is disposed within the interaction space 150 and about the cathode 140.

After the application of the operating potentials to the device 110, and after the cathode 140 has been heated to the operating temperature thereof by the heater 151, electrons are emitted from the emissive coating 146, the electrons being emitted into the interaction space 150 where they are subjected to the action of the unidirectional fields and the RF fields described hereinabove. There is also illustrated in FIG. 16 a diagrammatic representation of typical paths 294 of electrons emitted from the cathode projections 147, as illustrated the electrons following a spiral path in which the initial direction of flow is in a clockwise direction due to the influence of the unidirectional magnetic field. Eventually, the spiral paths 294 of the electrons carries them into contact with the anode 111 or the rods 130, whereby to complete an electrical circuit through the device 110. During the time that the electrons were in the spiral paths 294, they impart a portion of the energy content thereof to the RF standing wave within the spiral path and add power thereto and reinforce the RF standing wave.

There is illustrated in FIG. 18 a modified oscillator 200B which is constructed and arranged like the oscillator 200 described above, but differs in that the tuned cavity thereof has the frequency of operation thereof adjustable. More specifically, a first tuned circuit 280B is provided at the upper end of the device 110 and includes an outer conductor 82 and an inner conductor 282B providing a section of a coaxial transmission line, the outer conductor 82 being capacitively coupled by the coupler 80 to the annular conductor 107 that is directly connected to the anode 111, and the inner conductor 282B being capacitively coupled to the terminal 102 that is directly connected to the cathode 140. The outer end of the thus formed coaxial transmission line is shorted by means of an RF short 283B extending therebetween and closing the outer end thereof.

There is provided at the other end of the device 110 a second tuned circuit 285B in the form of a coaxial transmission line including an outer conductor 108 and an inner conductor 288B, the outer conductor 108 being directly connected to the anode 111 and the inner conductor 288B being capacitively coupled to the terminal 103 that is capacitively coupled to the adjacent end of the cathode 140. The outer end of the coaxial transmission line thus formed is closed and shorted by an RF short 289B, the RF short 289B being in sliding engagement and in electrical contact with the facing surfaces of the conductors 108 and 288B, whereby the RF short 289B is slideable in a vertical direction as connected by the arrows. In order to permit the position of the RF short 289B to be manually adjusted, a control rod 286B is provided having one end thereof threadedly connected to the RF short 289B and having on the outer end thereof a knurled handle 287B. By adjusting the position of the RF short 289B, the length of the tuned cavity of the oscillator 200B, i.e., the distance between the facing surfaces of the RF shorts 283B and 289B is adjusted, thereby to adjust and change the frequency of operation of the oscillator 200B.

Recapitulating, the tuned circuits 280B and 285B, which comprise the resonant circuit of the oscillator 200B, are each formed by an inner conductor and an outer conductor, the conductors of the tuned circuit 280B extending outwardly in one direction from the longitudinal midplane of the device 110 and being connected together at the outer ends thereof by an RF short 283B, and the conductors of the tuned circuit 285B extending outwardly in the opposite direction from the longitudinal midplane of the device 110 and being connected together at the outer ends thereof by an RF short 289B, the total distance from the RF short 283B to the RF short 289B being equivalent to one-half of the wavelength of the desired frequency of operation of the oscillator 200B.

An oscillator also can be formed by connecting a section of coaxial transmission line between the rods 130 and the cathode 140 to provide a cavity that is resonant at the desired operating frequency. Such a connection is illustrated in FIG. 19 of the drawings, wherein an oscillator 300 is illustrated incorporating therein the device 110 connected as an oscillator and supplying microwave energy to the output transmission line 64. The oscillator 300 includes a first resonant cavity 380 connected to the upper end of the device 110 and including an outer conductor 382 and an inner conductor 102 that cooperate to form a coaxial transmission line. The conductor 382 is directly connected to the seal member 166 which is in turn directly connected to the adjacent ends of the rods 130, and the conductor 102 is directly connected to the adjacent end of the cathode 140. To form the tuned resonant cavity 380, an RF short 383 is provided between the concentric conductors 382 and 102 at a point spaced a predetermined distance from a plane normal to the axis of the anode 111 midway between the end walls 113 and 114 thereof, the predetermined distance being equivalent to one-fourth of the wavelength of the desired frequency of operation of the oscillator 300.

Another tuned circuit 385 is provided at the other end of the device 110 and is in the form of a coaxial transmission line including an outer conductor 388 and an inner conductor 103. The outer conductor 388 is directly connected to the seal member 166 that is in turn directly connected to the adjacent ends of the rods 130, and the inner conductor 103 is capacitively coupled to the adjacent end of the cathode 140. An RF short 389 is provided at the lower end of and capacitively coupling the coaxial conductors 388 and 103 to complete the tuned circuit 385. Preferably the inner surface of the RF short 389 is disposed from the midpoint of the device 110 a distance equivalent to one-fourth of the wavelength of the desired frequency of operation of the oscillator 300. The tuned circuits 380 and 385 cooperate with the device 110 to form a continuous tuned cavity having a length equal to one-half of the wavelength of the frequency of operation of the oscillator 300.

Recapitulating, the tuned circuits 380 and 385, which comprise the resonant circuit of the oscillator 300, are each formed by an inner conductor and an outer conductor, the conductors of the tuned circuit 380 extending outwardly in one direction from the longitudinal midplane of the device 110 and being connected together at the outer ends thereof by an RF short 383, and the conductors of the tuned circuit 385 extending outwardly in the opposite direction from the longitudinal midplane of the device 110 and being connected together at the outer ends thereof by an RF short 389, the distances from the midplane of the device 110 to the RF shorts 383 and 389 each being equivalent to one-fourth of the wavelength of the desired frequency of operation of the oscillator 300.

Upon the establishment of the unidirectional electrical and magnetic fields in the device 110, the tuned cavity including the tuned circuits 380 and 385 in the oscillator 300 resonates at a frequency having a wavelength equal to twice the distance between the surfaces of the RF shorts 383 and 389, i.e., a standing RF wave is established within the tuned cavity and extends axially thereof and axially of the device 110 and through the interaction space thereof. It is believed that there is associated with the standing RF wave thus established an RF electrical field disposed normal to the axis of the device 110, a diagrammatic representation of the field being illustrated in FIG. 20. From FIG. 20, it will be seen that at any moment, the rods 130 have one RF polarity while the cathode 140 has the opposite RF polarity. Accordingly, there is a relatively strong RF field between the rods 130 and the cathode 140 and also between the anode segments 115 and the cathode 140, and a relatively weak RF field between the anode 111 and the rods 130. In FIG. 20, the instantaneous RF electrical field has been designated by the numeral 390, and the portion thereof disposed between the rods 130 and the cathode 140 has been

designated 390c, the force lines being disposed normal to the surfaces of the rods 130 and the outer surfaces 148 of the cathode 140. There is a slightly weaker RF field between the anode segments 115 and the cathode 140, that field being designated by the numeral 390b, the force lines representing the field 390b being normal to the outer surfaces 117 and the outer surfaces 148. Finally, there is a much weaker RF electrical field between the anode 111 and the rods 130, that field being designated 390a, the force lines representing the field 390a also being disposed normal to the outer surfaces of the rods 130 and normal to the surface of the recess 116.

It is believed that there is associated with the RF electrical field 390 of the standing RF wave in the oscillator 300 an RF magnetic field 392 which is illustrated in FIG. 21. The magnetic field 392 is also disposed normal to the axis of the device 110 and normal to the RF electrical field 390 and includes a first field 392a surrounding the rods 130 and a second and stronger field 392b surrounding the cathode 140 and disposed in the interaction space 150. In fact, the major portion of the RF magnetic field 392 is disposed within the interaction space 150 and about the cathode 140.

After the application of the operating potentials to the device 110 and after the cathode 140 has been heated to the operating temperature thereof by the heater 151, electrons are emitted from the emissive coating 146, the electrons being emitted into the interaction space 150 where they are subjected to the action of the unidirectional fields and the RF fields described hereinabove. There is also illustrated in FIG. 20 a diagrammatic representation of the typical paths 394 of electrons emitted from the cathode projections 147, as illustrated the electrons flowing in a spiral path in which the initial direction of flow is in a clockwise direction due to the influence of the unidirectional magnetic field. Eventually, the spiral paths 394 of the electrons carries them into contact with the anode 111 or the rods 130, whereby to complete an electrical circuit through the device 110. During the time that the electrons are in the spiral paths 394, they impart a portion of the energy content thereof to the RF standing wave and add power thereto and reinforce the RF standing wave.

There is illustrated in FIG. 22 a modified oscillator 300A which is constructed and arranged like the oscillator 300 described above, but differs in that only tuned circuit is provided between the rods 130 and the cathode 140, that tuned circuit being disposed at the top of the device 110 in FIG. 22 and being designated by the numeral 380A. More specifically, the tuned circuit 380A includes an outer conductor 382A and an inner conductor 102, the outer conductor 382A being directly connected to the seal member 166 that is in turn directly connected to the adjacent ends of the rods 130, and the inner conductor 102 is directly connected to the cathode 140. In order to complete the tuned circuit 380A, an RF short 383A is provided at the outer end of the coaxial transmission line including the conductors 382A and 102. The inner surface of the RF short 383A is a predetermined distance from the end wall 114 of the device 110, the predetermined distance being equivalent to one-fourth of the wavelength of the frequency of operation of the oscillator 300A. The other end of the device 100 has no tuned circuit associated therewith, the coaxial transmission lines formed by the cooperation of the rods 130 and the cathode 140 being open at the lower end thereof as viewed in FIG. 22. Accordingly, the oscillator 300A has but a single tuned cavity including the tuned circuit 380A and the interior of the device 110, the tuned cavity having a length equal to one-fourth of the wavelength of the operating frequency of the oscillator 300A.

There is illustrated in FIG. 23 a further modified oscillator 300B which is constructed and arranged like the oscillator 300 described above, but differs in that the tuned cavity thereof has the frequency of operation thereof adjustable. More specifically, a first tuned circuit 380B is provided at the upper end of the device 110 and includes an outer conductor 382B and an inner conductor 102 providing a section of a coaxial transmission line, the outer conductor 382B being directly

connected to the seal member 166 that is in turn directly connected to the adjacent ends of the rods 130, and the inner conductor 102 being directly connected to the adjacent end of the cathode 140. The outer end of the thus formed coaxial transmission line is shorted by means of an RF short 383B extending therebetween and closing the outer end thereof.

There is provided at the other end of the device 110 a second tuned circuit 385B in the form of a coaxial transmission line including an outer conductor 388B and an inner conductor 103, the outer conductor 388B being directly connected to the seal member 166 that is in turn directly connected to the adjacent ends of the rods 130, the inner conductor 103 being capacitively coupled to the adjacent end of the cathode 140. The outer end of the coaxial transmission line thus formed is closed and shorted by an RF short 389B having an annular insulator 384B disposed therein, the RF short 389B being in sliding engagement with the facing surfaces of the conductors 388B and 103, whereby the RF short 389B is slideable in a vertical direction as indicated by the arrows. In order to permit the position of the RF short 389B to be manually adjusted, a control rod 386B is provided having one end thereof threadedly connected to the RF short 389B and having on the outer end thereof a knurled handle 387B. By adjusting the position of the RF short 389B, the length of the tuned cavity of the oscillator 300B, i.e., the distance between the facing surfaces of the RF shorts 383B and 389B is adjusted, thereby to adjust and change the frequency of operation of the oscillator 300B.

Recapitulating, the tuned circuits 380B and 385B, which comprise the resonant circuit of the oscillator 300B, are each formed by an inner conductor and an outer conductor, the conductors of the tuned circuit 380B extending outwardly in one direction from the longitudinal midplane of the device 110 and being connected together at the outer ends thereof by an RF short 383B, and the conductors of the tuned circuit 385B extending outwardly in the opposite direction from the longitudinal midplane of the device 110 and being connected together at the outer ends thereof by an RF short 389B, the total distance from the RF short 383B to the RF short 389B being equivalent to one-half of the wavelength of the desired frequency of operation of the oscillator 300B.

The graphs of FIGS. 24 to 26, inclusive, illustrate certain important operating characteristics of the device 110. Referring first to FIG. 24, there is plotted therein the voltage developed across a 10,000-ohm resistor connected between the rods 130 and the cathode 140 as a function of the current through the magnet coils 131 and 135 for different values of applied B+ potential, the voltage on the rods 130 (i.e. across the resistor) being plotted along the vertical axis and the current through the magnet coils 131 and 135 being plotted along the horizontal axis. In FIG. 25 there is illustrated the effect of different values of applied B+ potential on the anode upon the anode current for the values of bias on the rods 130, the anode voltage being plotted along the vertical axis and the anode current being plotted along the horizontal axis. Finally, there is plotted in FIG. 26 the power output for different ratios of anode current to rod current when the anode is connected to the rods by means of a 100-ohm resistor. More specifically, there is plotted along the vertical axis the ratio of the anode current to the rod current and the corresponding percentage of rod current, and plotted along the horizontal axis is the output power in watts.

At a frequency of operation of 910 megacycles of the oscillator 100 with an applied B+ potential of 775 volts, a power output of 700 watts was obtained with 2 amperes of series magnet field current, resulting in 35 percent efficiency. It further was found that with the application of 400 volts to the rods 130, the RF power could be 100 percent modulated by decreasing the rod potential to 350 volts.

As has been pointed out above, the device 110 essentially functions as an open ended coaxial transmission line, whereby the frequency of the axially extending RF wave disposed therein is dependent upon the point along the line at which the

line is terminated to provide a reflecting surface for the RF wave to form a standing RF wave within the device 110 and its associated tuned circuits. In addition there theoretically can be rotating mode frequencies in the device 110 that can be expressed by the equation:

$$\frac{f}{f_0} = \sqrt{2} \left(1 - \cos \frac{2\pi n}{N} \right)$$

wherein, f is the observed frequency at which oscillations can be established in the tuned circuit, f_0 is the frequency of the tuned circuit, n is the mode number and N is the number of rods 130, namely, fifteen. This equation is based upon an analysis of the system as a reentrant capacitively loaded line wherein one side of a line is represented by the anode 111 and the other side of the line is represented by the rods 130; the capacitance is that between the rods 130 and the anode 111. In operation as an oscillator, none of the rotational modes are observed, but rather the device 110 operates in modes characteristics of a plain coaxial triode, such as $\lambda/4$, $3\lambda/4$, $5\lambda/4$, etc., for a single-ended cavity and $\lambda/2$, $3\lambda/2$, $5\lambda/2$, etc., for a double-ended cavity. Both the operational modes and the rotational modes have been observed on cold test while only the operational modes have been observed on hot tests of the device 110. When loading the device 110 out of oscillation, the anode current goes to zero which indicates the absence of mode shift; this is indicative of exceptionally good mode stability. A further advantage of the device 110 resides in that the permissible heavy loading allows low Q operation that is necessary to obtain broad band operation or a wide tuning range when using tunable cavities.

In a constructional example of the crossed-field discharge device 110, the various parts thereof have the following dimensions; the anode 111 has an external diameter of $1\frac{1}{8}$ inch, a length between the end walls 113 and 114 thereof of $1\frac{1}{4}$ inch, a distance from the longitudinal axis to the surfaces 117 of three-eighths inch, a distance from the longitudinal axis to the surfaces 119 of one-half inch, a radial dimension of the recesses 116 of one-eighth inch, a circumferential dimension of the recesses 116 of one-eighth inch and a circumferential dimension of the surfaces 117 of three thirty-seconds inch. The rods 130 have a diameter of one-sixteenth inch and a length between adjacent surfaces of the pole pieces 120 of $1\frac{1}{2}$ inch; and the inner surfaces 130a thereof are spaced outwardly with respect to the adjacent surfaces 117 0.005 inch. The cathode has an overall diameter of twenty-one thirty-seconds inch and a length of $1\frac{9}{32}$ inches; the projections 147 have a radial extent of one thirty-second inch; the surfaces 148 have a circumferential extent of one thirty-second inch and the spaces 149 have a circumferential extent of one thirty-second inch. The spacing between the anode surfaces 117 and the cathode surfaces 148 is one-sixteenth inch; the angular displacement between the centerline of a cathode projection 147 and the centerline of the adjacent anode segment 115 or rod 130 is 3° . The pole pieces 120 have a longitudinal extent nineteen thirty-seconds inch, the diameter of the surface 121 is twenty-three thirty-seconds inch, and the outer diameter of the annular projection 122 is 1 inch. The longitudinal extent of the seal member 161 is three-eighths inch, the longitudinal extent of the seal member 166 is five-sixteenths inch, the longitudinal extent of the ceramic discs 164 and 165 is one-eighth inch and the external diameter thereof fifteen-sixteenths inch. The longitudinal extent of the insulating sleeves 173 is 1 inch and the external diameter thereof is three-eighths inch.

Referring now to FIG. 27 of the drawings, there is diagrammatically illustrated the manner in which the output of the oscillator circuit 50 can be connected to the input of an amplifying circuit 400 which embodies therein certain additional features of the present invention. Inasmuch as the construction and operation of the power supply 51 and the oscillator 100 in the circuit of FIG. 27 are identical to those described above, the description will not here be repeated. It will be understood that the output of the oscillator 100 is applied to a

coaxial transmission line 410 which has the outer conductor thereof connected to the coupler 80 and which has the inner conductor thereof connected to the capacitive coupler 83. The transmission line 410 is in turn connected by capacitive couplers 425 to a cavity 430 and a radiating probe 413 is connected to the transmission line 410 and arranged to radiate into the cavity 430 connected to the amplifying circuit 400. The amplifying circuit 400 incorporates therein a crossed-field discharge device 110 of the type set forth above, the amplifying circuit 400 having a pair of input terminals 401 and 402 that are connected respectively to the DC output terminals 56 and 57 of the power supply 51 by means of the conductors 60 and 61, respectively; the input terminal 402 is also connected by the conductor 61 to the low voltage AC output terminal 55 of the power supply 51. A third input terminal 403 is provided for the amplifying circuit 400, the input terminal 403 being connected by the conductor 62 to the other low voltage AC output terminal 54 of the power supply 51.

A pair of output terminals 447 and 450 is provided for the amplifying circuit 400, the output terminal 447 being connected by a capacitive coupling 445 to the outer conductor 65 of the output transmission line 64, and the output connection 450 being connected to the inner conductor 66 of the output transmission line 64. The capacitive coupling provided by the coupler 445 is desirable and necessary since the output terminal 447 is at a relatively high DC potential, whereby it is necessary electrically to isolate the output terminal 447 from the outer conductor 65 so that the outer conductor 65 can be grounded. As has been pointed out above, it is inherent in the construction and operation of the power supply 51 which is of the voltage doubler-rectifier type that neither the conductor 60 nor the conductor 61 can be grounded, whereby it is also not possible to ground the output terminals 447 and 450 of the amplifying circuit 400. Accordingly, it is also necessary and desirable that the amplifying circuit 400 be electrically shielded by a grounded outer housing (not shown) disposed therearound in order to prevent a user of the amplifying circuit 400 from being placed in contact with relatively high DC voltages if the user should accidentally come in contact with the amplifying circuit 400.

The microwave energy supplied from the amplifying circuit 400 to the transmission line 64 may be used for any desired purpose, two typical uses of the microwave energy being illustrated in FIG. 27, the first use being illustrated in the upper right-hand portion of FIG. 27 wherein the transmission line 64 is shown coupled to an antenna of the type commonly used in search radar, the outer conductor 65 being connected to outer radiating or antenna elements 67 and the inner conductor 66 being connected to a radiating or antenna element 68, the antenna elements 67 and 68 serving to match the impedance of the transmission line 64 to the impedance of the atmosphere. Alternatively, the microwave energy from the amplifying circuit 400 in the transmission line 64 may be utilized in an electronic heating apparatus such as the electronic range 70 illustrated that is especially designed for home use. The electronic range 70 in FIG. 27 is identical to the electronic range 70 described above with respect to FIG. 1 of the drawings, and accordingly, like reference numerals have been applied to like parts throughout. The microwave energy within the transmission line 64 is radiated into the internal cavity of the range 70 to provide the power for heating materials disposed therein. It further will be understood that in a preferred embodiment of the range 70, the power supply 51, the oscillator 100, and the amplifying circuit 400 together with the transmission line 64 are all preferably disposed within a common housing that also includes the casing 71, the common housing preferably being formed of metal and grounded for safety purposes.

Further details of the construction of the amplifying circuit 400 and the connection thereof to the crossed-field discharge device 110 incorporated therein will now be described with reference to FIG. 28 of the drawings. The construction of the crossed-field discharge device 110 incorporated in the amplifying circuit 400 of FIG. 28 is identical to the construction of

the crossed-field discharge device 110 described above with respect to the oscillator 100 and illustrated in detail in FIGS. 3 to 6 of the drawings, whereby like reference numerals have been applied to like parts throughout including the magnet coils 131 and 135, the magnetic yokes 132 and 136 and the associated mechanical and electrical connections. As illustrated, the input coaxial transmission line 410 includes an annular outer conductor 411 within which is disposed an inner conductor 412, the left-hand end of the outer conductor 411 communicating with an outer coaxial transmission line 420 that is connected to the upper end of the device 110. More specifically, the coaxial transmission line 420 includes an outer annular conductor 421 within which is disposed an annular inner conductor 422, the upper and outer ends thereof being interconnected and the space therebetween closed by an end wall 423. An opening is formed adjacent to the upper end of the outer conductor 421 and the outer conductor 411 is mechanically and electrically connected thereto in surrounding relationship with the opening. Connected between the input transmission line conductors is a radiating probe 413 that serves to radiate the microwave energy within the input transmission line 410 into the coaxial transmission line 420. The outer conductor 421 extends downwardly toward the upper end of the anode 111 and is capacitively coupled thereto by a coupler 425; more particularly, an outer annular conductor 427 is mechanically and electrically connected to the anode 111 and extends upwardly beyond the upper end of the magnetic yoke 132 and surrounds the adjacent portion of the outer conductor 421, an insulating and dielectric sleeve 426 being disposed between and substantially filling the annular space between the concentric conductors 421 and 427, the sleeve 426 being formed of a synthetic organic plastic resin, the preferred resin being a tetrafluoroethylene resin sold under the trademark "Teflon."

A second coaxial transmission line 430 is disposed within the coaxial transmission line 420 and includes an annular outer conductor 431 within which is disposed an annular inner conductor 432, the outer or upper end of the transmission line 430 being closed by a wall 433 extending between the conductors 431 and 432 and completely closing the space disposed therebetween. The outer conductor 432 extends downwardly and is in mechanical and electrical connection with and surrounds the seal member 166 that is in direct electrical connection with the adjacent ends of the rods 130 in the device 110, whereby to provide a direct connection between the outer conductor 431 and the rods 430. The outer conductor 431 is also capacitively coupled to the inner conductor 422 which surrounds the outer conductor 431 and is spaced therefrom to receive an annular sleeve 434 that fills the space therebetween, the sleeve 434 being formed of a dielectric material, the preferred material being a synthetic organic plastic resin and preferably a tetrafluoroethylene resin sold under the trademark "Teflon." The inner conductor 432 is capacitively coupled to a connector 402 that threadedly engages the connector 153 and extends upwardly therefrom and past the end wall 433, the conductor 432 completely surrounding the connector 402 and being spaced therefrom, the space between the conductor 432 and the connector 402 being filled by a dielectric sleeve 436, formed of a synthetic organic plastic resin, the preferred material being a tetrafluoroethylene resin sold under the trademark "Teflon." Finally, an annular cylinder 437 of dielectric material is disposed between the lower ends of the conductors 421 and 431 at the lower ends thereof, the cylinder 437 being formed of a synthetic organic plastic resin possessing dielectric properties, the preferred material being a tetrafluoroethylene resin sold under the trademark "Teflon."

The output from the amplifying circuit 400 is taken from the lower end of the crossed-field discharge device 110 and includes a first output conductor 440 that is tubular in shape and which is capacitively coupled to the anode 111 by a coupler 445, the coupler 445 including an outer annular conductor 447 that surrounds the conductor 440 and is mechanically and

electrically connected to the anode 111, the space between the conductors 440 and 447 being filled by an annular sleeve 446 of dielectric material, the sleeve 446 being formed of a synthetic organic plastic resin, the preferred resin being a tetrafluoroethylene resin sold under the trademark "Teflon." The outer end of the tubular conductor 440 (the lower end as seen in FIG. 28) is connected to the output transmission line 64, and specifically is connected to the outer conductor 65 and surrounds an opening in the upper wall thereof as viewed in FIG. 28.

A second output conductor 450 is provided that is also annular in shape and disposed within the conductor 440 and has the upper end thereof in mechanical and electrical connection with the seal member 166 that is in direct electrical connection with the adjacent ends of the rods 130. The lower end of the conductor 450 passes through an opening in the inner conductor 66 in the output transmission line 64. Disposed concentric with the conductor 450 is an inner tubular conductor 451 that is spaced therefrom, the space between the conductors 450 and 451 being filled by a sleeve 452 formed of dielectric material such as a synthetic organic plastic resin, the preferred resin being a tetrafluoroethylene resin sold under the trademark "Teflon." The upper end of the conductor 451 is spaced from the upper end of the conductor 450 a substantial distance, and the lower end of the conductor 451 is mechanically and electrically connected to the outer wall of the outer conductor of the transmission line 64 and surrounds an opening therein. Disposed within the conductor 451 is an output connector 403 which has the upper end thereof threadedly connected with the output connector 158 on the device 110, the lower end of the connector 403 extending downwardly through and beyond the transmission line 64, a solid annular block 458 of dielectric material closing the space between the connector 403 and the tubular conductor 451 adjacent to the outer ends thereof, the block 458 being formed of a synthetic organic resin, the preferred resin being a tetrafluoroethylene resin sold under the trademark "Teflon."

The conductor 60 that is connected to the output terminal 56 of the power supply 51 is connected as at 401 to one terminal of the magnet coil 131, whereby to apply the potential to the anode 111 of the device 110 through the magnet coil 131, the conductor 134, the magnet coil 135, the conductor 138 and the connection 139 on one of the cooling fins 129 that is electrically connected to the anode 111. The conductor 61 which is connected both to the output terminal 57 of the power supply 51 and one of the terminals 55 carrying the low voltage AC output for the heater 151 is attached to the connector 402 that is in turn directly connected to the cathode 140 through the connector 153. Finally, the other terminal 54 of the power supply 51 carrying the low voltage AC potential for the heater 151 is connected by the conductor 62 to the connector 403 that is in turn connected to the other end of the heater 151.

The microwave energy to be amplified in the amplifying circuit 400 is applied thereto through the input transmission line 410, and more particularly the probe 413 radiates into the coaxial transmission line 420 that is capacitively coupled both to the anode 111 and the rods 130, thereby to apply the input energy between the anode 111 and the rods 130. In order to provide a suitable match between the impedance of the transmission line 410 and the impedance of the amplifying circuit 400, the transmission line 420 preferably has a length equivalent to three-fourths of the wavelength of the energy to be amplified, i.e., the distance between the inner surface of the outer wall 423 and a plane normal to the axis of the device 110 and disposed midway between the end walls 113 and 114 of the anode 111 is equivalent to three-fourths of the wavelength of the energy to be amplified. It would also be permissible to connect the transmission line 410 at a point spaced one-fourth of a wavelength from the mid plane of the device 110, but it is not possible to make the necessary electrical connections at this point as illustrated in FIG. 28. The cylinder 437 provides additional capacitance between the anode 111

and the rods 130 to improve the mode stability. It further is pointed out that the coaxial transmission line 430 has a length slightly greater than that of the coaxial transmission line 420, the length of the transmission line 430 being a function of the interelectrode capacitance of the device 110 and the cathode 140 therein, the length of the transmission line 430 being adjusted for maximum output from the amplifying circuit 400.

The microwave energy thus injected into the upper end of the amplifying circuit 400 passes into the crossed-field discharge device 110 and specifically along the coaxial transmission line provided by the cooperation of the anode 111 and the rods 130 therein. As the microwave energy passes through the device 110, the RF fields associated therewith are reinforced and augmented by the action of the electrons that pass from the cathode 140 to the anode 111. It is believed that the amplifying circuit 400 operates in accordance with the M-type fast wave interaction principle, whereby the input microwave energy in passing through the interaction space 150 interacts with the fields disposed therein and the power content of the microwave energy is augmented and amplified so that a microwave energy output is obtained between the anode 111 and the rods 130 at the other end of the device 110 that has the same frequency as the microwave energy supplied through the input transmission line 410, but has the power content thereof substantially greater than the power content of the microwave energy supplied via the input transmission line 410, the power amplification being for example in the range from about 6 to 10. It has been found that the single interaction space 150 achieves this substantial amplification although the length thereof is on the order of about 0.1 times the wavelength of the energy being amplified, whereas prior devices have required lengths of the interaction space that are many times the wavelength of the microwave energy being amplified, for example as many as 20 times the length of the wavelength of the energy being amplified.

The output microwave energy appears between the conductors 440 and 450, the conductor 440 being capacitively coupled by the coupler 445 to the anode 111 and the conductor 450 being connected directly to the adjacent ends of the rods 130. The conductors 440 and 450 are respectively connected to the outer conductor 65 and the inner conductor 66 of the output transmission line 64.

It is pointed out that there is no cutoff frequency for the amplifying circuit 400 since the device 110 essentially comprises an open ended transmission line formed by the cooperation of the anode 111 and the rods 130, whereby a wide spectrum of microwave energy can be amplified utilizing the amplifying circuit 400. The power gain, however, is a function of the bandwidth of the system which is determined by the Q of the cavity which is formed by the cooperation of the input transmission line 420 and the device 110; a large bandwidth requires a lower Q and results in a lower power gain, and conversely, a small bandwidth requiring a higher Q results in a higher power gain. The power gain is also a function of the length of the interaction space 150 in the device 110, a greater length of the interaction space 150 providing greater power gain, and conversely, a smaller length of the interaction space 150 providing a smaller power gain.

To further illustrate the characteristics of the amplifying circuit 400, there are illustrated in FIG. 28 test connections to the input transmission line 410 and the output transmission line 64 by means of which other characteristics of the amplifying circuit 400 can be illustrated. The oscillator 100 as illustrated in FIG. 28 has the output thereof connected by a transmission line 470 to the input of an attenuator 472, a wave meter 471 also being connected to the transmission line 470 so that the frequency of the microwave energy supplied to the transmission line 470 can be monitored. The output from the attenuator 472 is applied by a transmission line 473 to the input of a tuner 474 which in turn has the output thereof connected to the input transmission line 410. The output transmission line 64 is connected to the input of an output tuner 475 that in turn is connected to a transmission line 476 con-

nected to a load 478 by which the power provided from the amplifying circuit 400 can be measured; also connected to the transmission line 476 is a wave meter 477 by which the frequency of the microwave energy within the transmission line 476 can be monitored.

In a first test of the amplifying circuit 400, the operating potentials were removed therefrom, i.e., the operating potentials applied via the conductors 60, 61 and 62 were removed; the input and output tuners 474 and 475, respectively, were adjusted to give maximum power transfer from the oscillator 100 into the load 478. When the operating potentials were than applied to the amplifying circuit 400 via the conductors 60, 61 and 62, the amount of microwave energy delivered to the load 478 was found to increase in proportion to the input power. The efficiency of amplification obtained was the same as that found when the device 110 was operated as a power oscillator as described above with reference to FIG. 2.

The frequency of the output energy delivered to the load 478 was then measured by means of the wave meter 477; it was found that a single frequency of microwave energy was present in the transmission line 476, that frequency being the frequency of operation of the oscillator 100 as determined by the wave meter 471. The frequency of operation of the oscillator 100 was then varied to determine if the frequency of the output was due to the tuning of the circuits in the amplifying circuit 400, and it was found that the output frequency of the amplified microwave energy as measured by the wave meter 477 varied directly in accordance with the variations in the frequency of operation of the oscillator 100 as determined by the wave meter 471, whereby it was concluded that there was no electronic tuning effect in the amplifying circuit 400. Further to verify that there was no operation of the amplifying circuit 400 as an oscillator, the operating potentials were removed from the oscillator 100 so that no output was obtained therefrom as measured by the wave meter 471. The output from the amplifying circuit 400 immediately dropped to zero indicating that there were no oscillations in the amplifying circuit 400, whereby to verify that the operation of the circuit 400 was truly as an amplifier and not as an oscillator.

Finally, the microwave energy to the amplifying circuit 400 was varied by means of the attenuator 472 over the range from 1 watt to 100 watts. It was determined that there was stable operation of the amplifying circuit 400 over the entire range of power input, the output from the amplifying circuit 400 as measured by the load 478 being directly proportional to the power supplied as an input to the amplifying circuit 400 via the input transmission line 410.

There further are illustrated in FIG. 28 additional connections to the amplifying circuit 400 to accommodate the application of modulating signals thereto. More specifically, there is provided a resistor 480 having one terminal thereof connected by a conductor 481 to the tubular conductor 427 that is connected to the anode 111 of the device 110, the conductor 481 also being connected to a terminal 482; and the other terminal of the resistor 480 is connected by a conductor 483 to the tubular conductor 431 that is connected to the rods 130, the conductor 483 also being connected to an input terminal 484. A second resistor 485 has one terminal thereof connected to the conductor 483 and the other terminal thereof connected to the conductor 61 and to an input terminal 486. Accordingly, it will be seen that the input terminal 482 is connected to the anode 111, the input terminal 484 is connected to the rods 130 and the input terminal 486 is connected to the cathode 140 of the device 110. A modulating signal can be applied between the input terminals 482 and 484, whereby to modulate the amplitude of the microwave energy supplied by the output of the amplifying circuit 400 to the output transmission line 64. Likewise, a modulating signal can be applied between the input terminals 484 and 486, and finally a modulating signal can be applied between the input terminals 482 and 486 also to modulate the amplitude of the microwave energy in the output of the amplifying circuit 400 that is supplied to the output transmission line 64.

There is illustrated in FIG. 29 of the drawings a crossed-field discharge device 510 that is a modification of the crossed-field discharge device 110, the device 510 differing from the device 110 fundamentally in the construction and arrangement of the cathode 540 thereof, whereby all of the other parts of the device 510 have the same construction and arrangement as the corresponding parts in the device 110; therefore like reference numerals in the 500 series have been applied to the parts in the device 510 that are identical in construction and arrangement to the parts in the device 110. The cathode 540 in the device 510 includes a cathode wall 541 conical in shape, the larger end of the conical wall 541 being disposed upwardly and the smaller end of the conical wall 541 being disposed downwardly. More specifically, the conical wall 541 is a section of a right cone and has the longitudinal axis thereof in alignment with the longitudinal axis of the anode 511 and the device 510.

A first end wall 542 is provided at the upper end of the cathode wall 541 and has a diameter slightly less than the diameter of the upper end of the wall 541 and is provided with an upwardly extending flange 542a, the flange 542a fitting within the associated end of the cathode wall 541 and being suitably connected thereto as by welding. A second smaller end wall 543 is disposed at the lower end of the cathode wall 541 and carries a downwardly extending flange 543 extending therearound and fitting within the associated end of the cathode wall 541 and being suitably secured thereto as by welding. The cathode wall 541 and the end walls 542 and 543 are all formed of a heat resistant and electrically conducting material, the preferred material of construction being nickel. The upper end wall 542 has a centrally disposed opening therein which receives the reduced portion on the lower end of the conductor 544, the lower end of the conductor 544 being mechanically and electrically secured to the end wall 542. The lower end wall 543 has a central opening therein which receives therethrough a portion of the insulating cylinder 557.

The cathode wall 541 is provided with sintered porous coating 546 impregnated with a suitable electron emissive oxide material, whereby upon heating of the cathode structure 540, the coating 546 readily emits electrons from the outer surface thereof. Preferably the coating 546 is provided with a plurality of outwardly extending projections (not shown) like the projections 147 described above, the projections on the coating 546 being oriented with respect to the anode segments 515 and the rods 530 in a manner like that described above when describing the relationship between the projections 147 and the anode segments 115 and the rods 130.

As illustrated, the cathode structure 540 is of the indirectly heated type, and accordingly, there has been provided within the conical cathode wall 541 a heater 551 in the form of a coiled filament extending substantially the entire length of the cathode wall 541 and spaced inwardly a short distance from the inner surface thereof; more particularly, the individual coils of the heater 551 are of decreasing diameter from the top to the bottom thereof with the outer surfaces of the heater 551 lying on a cone that is slightly smaller than the cathode wall 541. The upper end of the heater 551 has an outer end 552 that extends upwardly and through the conductor 544 to the outer connection 553, and the lower end of the heater 551 has an outer end 554 that is connected to the conductor 555 that is in turn connected to the connector 558.

The device 510 can be used both in the oscillator 100 described above and in the amplifying circuit 400 described above. When connected as an oscillator, the output transmission line 64 in FIG. 2 is connected to the upper end of the device 510, i.e., to the end of the device 510 wherein the cathode 540 is spaced the minimum distance away from the anode 511. It has been found that the energy output of the oscillator is materially increased by utilizing the device 510 therein. When utilizing the device 510 in the amplifying circuit 400 in FIG. 28, the input transmission line 410 and associated structure is connected to the lower end of the device

510 as illustrated in FIG. 29, i.e., to the end of the device 510 at which the cathode 540 is spaced the greatest distance away from the anode 511 and wherein the cathode 540 has the smallest diameter; and the output transmission line 64 and associated structure is connected to the upper end of the device 510 as illustrated in FIG. 29, i.e., to the end of the device 510 wherein the cathode 540 is spaced the minimum distance from the anode 511, and wherein the cathode 540 has the largest diameter thereof. Utilization of the device 510 in the amplifying circuit 400 results in an improved gain therethrough as compared to an amplifying circuit 400 incorporating the device 110 therein.

There is illustrated in FIGS. 30 to 34 of the drawings a further modified form of a crossed-field discharge device 610 made in accordance with and embodying the principles of the present invention, the crossed-field discharge device 610 being shown incorporated in an oscillator designated by the numeral 600. Referring specifically to FIGS. 31 to 34, it will be seen that the crossed-field discharge device 610 includes an anode 611, a pole piece 620, a plurality of rods 630, a cathode structure 640, an interaction space 650 and end structures 660 and 670. The anode 611 is formed of a metal having good electrical-conducting properties and good heat transmission qualities, the preferred material of construction for the anode 611 being copper. The anode 611 is essentially cylindrical in shape and has disposed about the outer surface thereof a cylindrical sleeve or wall 612 also formed of copper and extending upwardly and downwardly beyond end walls 613 and 614 at the opposite ends thereof. As may be best seen in FIG. 34, an axially extending opening is provided centrally in the anode 611, the inner surface to the anode 611 having a plurality of axially extending anode segments 615 thereon that project radially into the axially extending space within the anode 611 and providing therebetween a corresponding plurality of axially extending anode recesses 616, fifteen of the anode segments 615 and 15 of the corresponding recesses 616 being provided in the anode 611 as illustrated. Each of the anode segments 615 has an axially extending inner surface 617 and a pair of outwardly curved sidewalls which meet with the sidewalls of adjacent anode segments 615 to provide a curved wall 618 that is also the wall defining the associated recess 616. The circumferential extent of the inner surfaces 617 is substantially less than the radial depth of the recesses 616 and is also substantially less than the circumferential distance between adjacent inner surfaces 617. As illustrated, each of the recesses 616 is substantially semicircular in cross section.

In order to remove the heat from the anode 611 during the operation of the device 610, the cylindrical wall 612 is preferably placed in good heat-conductive relationship to the anode 611. There is disposed on the outer surface thereof a plurality of outwardly and radially extending cooling fins 629, ten of the fins 629 being illustrated in FIGS. 27 and 28 of the drawings in a stacked array wherein the fins are spaced substantially equidistantly one from the other. The fins 629 are formed of a good heat-conducting material such as copper and are both in mechanical and heat transfer connection with the wall 612, the fins 629 preferably being brazed upon the outer surface of the wall 612. The shape of the fins 629 is such that they fit within the casing 605 provided for the device 610, there preferably being provided means for passing a cooling fluid, such as a stream of air, through the casing 605 and over the fins 629 to effect cooling thereof and a consequent removal of heat from the anode 611 and the other parts of the device 610 during the operation thereof.

Mounted adjacent to the upper end of the anode 611 is the pole piece 620, the pole piece 620 including a generally circular upper portion that emerges with a downwardly curved side flange 621 that in turn emerges with an outwardly directed flange 622, whereby the pole piece 620 completely covers the axial opening through the anode 611. Formed in the center of the pole piece 620 is an opening that receives therethrough a cylindrical conductor 623 arranged substantially axially of the

device 610 and being formed of a good electrical conducting material such as copper. The lower end of the conductor 623 carries an outwardly extending flange 624 (see FIG. 30 also), which has a plurality of projections 624a therein that are shaped complementarily to the recesses 616 in the anode 611, each projection 624a overlying an associated recess 616. Formed in each of the projections 624a is an opening 624b that receives therethrough the upper end of a rod 630, the associated rod 630 being mechanically and electrically connected to the associated projection 624b. The number of the projections 624a corresponds to the number of recesses 616 and the number of rods 630 also correspond to the number of recesses 616, whereby there are 15 of the rods 630 provided, each of the rods 630 being disposed essentially centrally with respect to the associated recess 616 (see FIG. 34 also), but having the inner edge 630a thereof disposed slightly outwardly with respect to the inner surfaces 617 on the adjacent anode segments 615. As illustrated, the rods 630 are cylindrical in shape and circular in cross section, the diameter of each of the rods 630 being approximately equal to one-half of the dimensions of an associated recess 616. The rods 630 each extend downwardly through the associated recess 616 and the lower ends thereof are mounted upon an annular ring 626, the ring 626 having openings 626a therein that receive the lower ends of the rods 630 which are mechanically and electrically connected to the ring 626. It will be seen that the conductor 623 electrically interconnects the upper ends of all of the rods 630 and the ring 626 likewise electrically interconnects the ends of all of the rods 630, the ring 626 preferably being formed of copper. Also disposed about the lower end of each of the rods 630 is a conically shaped insulator 627 formed of ceramic and in abutting engagement with the plate 626, the rods 630 and the anode 611, whereby to assist in accurately positioning the associated rod 630 in the proper relationship to the associated anode segments 615.

In order to establish a unidirectional magnetic field extending axially through the space within the anode 611, there has been provided a pair of magnetic coils 631 and 635, the magnet coil 631 being disposed about the upper portion of the device 610 as seen in FIG. 30 and the other magnet coil 635 being disposed about the lower end of the device 610. The coils 631 and 635 are each shaped as a torous, are wound of electrically conductive wire, and as illustrated, are disposed respectively about magnetic yokes 632 and 636 in the form of cylinders that are disposed within the openings in the associated coils and in turn have inner openings therein having diameters equal substantially to, or slightly greater than, the external diameter of reduced end portions 612a and 612b on the ends of the outer wall 612, the end portions 612a and 612b being telescopically received in the associated magnetic yoke 632 or 636. There further are provided outwardly extending flanges 633 and 637, respectively, on the yokes 632 and 636, and interconnecting the yokes 632 and 636 is the casing 605. It will be understood that the pole piece 620, the magnetic yokes 632 and 636, the flanges 633 and 637 and the casing 605 are all formed of metals that have a high magnetic permeability, whereby when the magnet coils 631 and 635 are energized, a strong and uniform unidirectional magnetic field is established by the pole piece 620 within the device 610 and extending axially therethrough.

The circuit for energizing the coils 631 and 635 can be traced from the conductor 60 to an input terminal 601 to which is connected one terminal of the magnet coil 631, the other terminal of the magnet coil 631 being connected by a conductor 634 to one terminal of the magnet coil 635, and the other terminal of the magnet coil 635 being connected by a conductor 638 to one of the cooling fins 629 by means of a connection 639, the cooling fin 629 being in direct connection with the anode 611. The current through the magnet coils 631 and 635 serves to produce the unidirectional magnetic field within the crossed-field discharge device 610.

A cathode structure 640 is provided in the axially extending space defined by the anode 611, the cathode structure 640 in-

cluding a cylindrical wall 641 arranged with the axis thereof disposed at the axis of the anode 611. A first end wall 642 is provided at the upper end of the wall 641 and is provided with an upwardly extending flange 642a, the flange 642a fitting within the upper end of the wall 641 and being suitably connected thereto as by welding. A second end wall 643 is disposed at the lower end of the wall 641 and is provided with a downwardly extending flange 643a, the flange 643a fitting within the lower end of the wall 641 and being suitably secured thereto as by welding. The wall 641 and the end walls 642 and 643 are all formed of a heat resistant and electrically conducting material, the preferred material of construction being nickel. The upper end wall 642 has centrally disposed therein and connected thereto a heat shield 645 that extends laterally outwardly and overlies the associated end of the cathode structure 640.

The outer surface of the wall 641 is provided with a sintered porous coating 646 impregnated with a suitable electron emissive oxide material, whereby upon heating of the cathode structure 640, the coating 646 readily emits electrons from the outer surface thereof. Referring particularly to FIG. 34 it will be seen that the coating 646 is shaped to provide a plurality of outwardly extending projections 647 each having outwardly converging sidewalls joining an essentially circumferentially arranged outer surface 648, a space 649 being provided between adjacent cathode projections 647. As illustrated, the circumferential extent of the outer surfaces 648 is substantially equal to the spacing 649 between adjacent projections 647. The preferred range of the circumferential extent of the outer surfaces 648 is approximately 25 percent to 60 percent of the circumferential distance between the centers of adjacent outer surfaces 648. The radial dimensions of each of the projections 647 is also preferably greater than about 20 percent of the spacing between the anode 611 and the coating 646 on the cathode structure 640. The number of projections 647 provided on the coating 646 is equal to the sum of the number of the anode segments 615 and the number of the rods 630, whereby there are 30 of the projections 647 provided upon the coating 646. The outer surfaces of the coating 646 together with the inner surfaces of the anode 611 define an interaction space 650 disposed therebetween in which the emitted electrons from the coating 646 interact with the electrical and magnetic fields disposed between the anode 611 and the cathode structure 640. The projections 647 combine with the anode segments 615 and the rods 630 to provide a preferred distribution of the several fields within the interaction space 650 of the device 610 that results in more desirable operating characteristics of the device 610. One particularly desirable result of the shape of the coating 646 as described is to minimize back heating of the cathode 640, the desirable emitted electrons emanating from the projections 647, and very few undesirable electrons emanating from the space 649 between the projections 647, thereby to facilitate the emission of desirable electrons and to suppress the emission of undesirable electrons.

In addition, the center line of each projection 647 is circumferentially displaced relative to the center line of its corresponding anode segment 615 or rod 630, as the case can be; more specifically, the center lines of the projections 647 are displaced in a clockwise direction a circumferential distance equal to approximately 40 percent of the circumferential space between the center lines of an adjacent anode segment 615 and an adjacent rod 630. The circumferential displacement of the projections 647 with respect to the corresponding anode segments 615 or rods 630 is preferably in the range between 0 percent and approximately 45 percent of the circumferential spacing between adjacent anode segments and rods, a preferred range being between 25 percent and approximately 45 percent of the spacing between adjacent anode segments and rods, a still more preferred range being between approximately 35 percent and 45 percent of the spacing between adjacent anode segments and rods, and on the downstream side, i.e., in the direction of normal initial electron flow from

the projections 647. Finally, it will be understood that the electrons emissive coating 646 is confined within the ends 613 and 614 of the anode 611, the cathode structure 640 being carefully centered with respect to the anode structure 611 and the rods 630. And to this end, the ceramic members 627 surrounding the lower ends of the rod 630 also engage the lower end of the cathode structure 640 and serve to assist in maintaining the desired alignment among the anode 611, the rods 630 and the cathode structure 640.

As illustrated, the cathode structure 640 is of the indirectly heated type, and accordingly, there has been provided within the cathode wall 641 a heater 651 in the form of a coiled filament extending substantially the entire length of the wall 641 and spaced inwardly a short distance from the inner surface thereof. The lower end of the heater 651 has an outer end 652 that extends downwardly through and into an opening in the upper end a conductor 602 and is mechanically and electrically connected thereto, the conductor 602 extending downwardly and terminating in a connection 653. The upper end of the conductor 602 is also in mechanical and electrical connection with the cathode end wall 643, whereby the connection 653 is in electrical contact with both the cathode structure 640 and the heater 651. The upper end of the heater 651 is connected to a downwardly extending conductor 654 that passes through an opening 657 in the cathode end wall 643 and is received in an opening in the upper end of a conductor 603, the lower end of the conductor 603 carrying a connector 658 thereon. It will be seen therefore that the connector 658 is connected only to one end of the heater 651 and is not connected to the cathode 640.

A first end structure 660 closes and hermetically seals the upper end of the anode 611, and specifically the upper end of the wall 612, the upper end of the wall 612 carrying the upwardly extending reduced portion 612a thereon that cooperates with the end structure 660. The end structure 660 includes a first sealing member 661 that is generally cylindrical in shape and has the axis thereof in alignment with the axis of the anode 611. The sealing member 661 is preferably formed of a "Fernico" alloy that can be readily joined both to the copper anode wall 612a and to ceramic sleeves. The lower end of the member 661 has an outwardly directed flange 662 therein that terminates in an upwardly directed flange 663 extending therearound and disposed within the wall portion 612a and hermetically sealed thereto as by brazing or the like. The upper end of the sealing member 661 has an inwardly directed flange 664 terminating in an upwardly extending annular flange 665 surrounding and sealed to the lower end of an insulator 666 that is preferably formed of ceramic. The insulator 666 is cylindrical in shape and has an opening therethrough receiving the conductor 623 therein. The connector 625 on the upper end of the conductor 623 is hermetically sealed to the upper end of the insulator 666 by means of a sealing member 687 of a "Fernico" alloy having an opening centrally therethrough and surrounding the lower end of the connector 625 and being hermetically sealed thereto, the outer edge of the sealing member 687 carrying a downturned flange which is hermetically sealed to the upper end of the insulator 666.

A second end structure 670 is provided at the lower end of the anode 611, the anode wall 612 more specifically having the downwardly extending reduced portion 612b thereon that cooperates with a sealing member 671. The sealing member 671 is preferably formed of a "Fernico" alloy that can be readily joined both to the copper anode wall 612b and to ceramic sleeves, and is generally cylindrical in shape and has the axis thereof in alignment with the axis of the anode 611. The upper end of the sealing member 671 has an outwardly directed flange 672 which carries a downwardly extending flange 673 fitting within the wall portion 612b and connected thereto as by brazing. The lower end of the sealing member 672 is closed by a wall 674 having a pair of openings therein surrounded by dependent flanges 675. The right-hand flange 675 receives therein an insulating sleeve 676 formed of

ceramic, a hermetic seal being provided between the flange 675 and the outer surface of the sleeve 676. An opening provided centrally in the sleeve 676 receives therethrough the conductor 602 which extends downwardly beyond the lower end thereof. A sealing member 678 formed of the same material as the sealing member 671 provides a hermetic seal between the lower end of the ceramic sleeve 676 and the lower end of the conductor 602 and the connection 653 thereon. The other dependent flange 675 receives a second insulating sleeve 677 formed of ceramic therein, a hermetic seal being formed between the flange 675 and the ceramic sleeve 677 adjacent to the upper end thereof. A longitudinal opening is formed centrally of the ceramic sleeve 677 that receives therein the conductor 603 which extends outwardly beyond the lower end thereof and carries on the lower end thereof the connection 658. A sealing member 679 formed of the same material as the sealing member 671 provides a hermetic seal between the lower end of the ceramic sleeve 677 and the lower end of the conductor 603 and the connection 658 attached thereto.

It will be understood that the end structures 660 and 670 each hermetically seals the associated end of the device 610 and also provides electrical connections between parts where desired, while providing electrical insulation between other parts where necessary. Further, it is often desirable to provide gaskets or other like constructions between contacting surfaces when formed of different materials, all as is well understood in the art.

Referring now to FIG. 30 of the drawings, the manner in which the crossed-field discharge device 610 is incorporated in the oscillator 600 will be described in further detail. A tubular conductor 607 is provided formed of a material that is electrically conductive, the preferred material being aluminum metal; the conductor 607 has an internal diameter slightly greater than the external diameter of the anode wall section 612a and is placed in telescoping relationship with the upper end thereof and is electrically connected thereto, the conductor 607 being disposed within the upper magnetic yoke 632 and extending upwardly to a point slightly below the upper end thereof. The upper connector 625 is threadedly received in a complementarily threaded opening in the lower end of a connector 628 extending upwardly therefrom, whereby the connector 628 is connected to the rods 630. In order to provide a tuned circuit for the oscillator 600, there is connected between the anode 611 and the rods 630 a tuned circuit 680 in the form of a section of coaxial transmission line, the tuned circuit 680 more particularly including an outer conductor 681 and an inner conductor 682, the outer ends of the conductor 681 and 682 being electrically shorted and the space therebetween closed by a conductive end wall 683. The outer conductor 681 is coupled to the conductor 607 by being arranged in telescoping relationship therewith. The inner conductor 682 is likewise coupled to the rods 630 and more particularly to the upstanding connector 628 connected thereto, the conductor 682 being in surrounding telescoping relationship with the connector 628.

In order to remove microwave energy from the tuned circuit 680, the output transmission line 64 is provided having an outer tubular conductor 65 and an inner conductor 66. The outer conductor 65 is connected at the lefthand end to the outer conductor 681 and surrounds an opening therein; the inner conductor 66 carries a coupling loop 684 that is disposed within the tuned circuit 680 and is connected between the outer conductor 65 and the inner conductor 66 of the output transmission line 64.

The threaded connections 653 and 658 at the lower end of the device 610 in the oscillator circuit 600 are threadedly connected to a pair of terminals 686 and 687, respectively, that extend outwardly beyond the lower end of an outer conductor 608 that is connected to the lower end of the anode 611 and disposed in telescoping relationship with the annular magnetic yoke 636. The terminal 686 constitutes a combination cathode and cathode heater terminal and the terminal 687

constitutes only a cathode heater terminal. The two terminals 686 and 687 are secured in place with respect to an associated support plate 688 by an assembly 690 formed of a stack of insulators 691, 692, 693 and 694 and of intervening conductive plates 695, 696 and 697, whereby the assembly 690 constitutes an RF capacitive shunt for the terminals 686 and 687 to ground potential for the RF frequency within the device 610. In passing it is noted that in FIG. 30 the relative thicknesses of the elements 691 to 697, inclusive, are substantially exaggerated for the purpose of illustration. In the arrangement, the terminals 686 and 687, respectively, carry two annular shoulders 686a and 687a that are arranged between the lower magnetic flange 637 and the plate 688. The shoulder 686a carried by the terminal 686 engages the adjacent upper surface of the insulator 691, and the outer end of the terminal 686 carries a speed nut 698 disposed in frictional engagement with the lower surface of the insulator 694, thereby to retain together the stacked elements 691 to 697, inclusive. Similarly, the shoulder 687a carried by the terminal 687 engages the adjacent upper surface of the insulator 691, and the outer end of the terminal 687 carries a speed nut 699 disposed in frictional engagement with the lower surface of the insulator 694, thereby to retain together the stacked elements 691 to 697, inclusive.

The conductive plate 695 has a small opening therein through which the shank of the terminal 687 extends in frictional contact therewith so that the conductive plate 695 is electrically connected to the terminal 687; and the conductive plate 695 has a large opening therein through which the shank of the terminal 686 extends in spaced relation so that the conductive plate 695 is electrically insulated from the terminal 686. Similarly, the conductive plate 696 has a small opening therein through which the shank of the terminal 686 extends in frictional contact therewith so that the conductive plate 697 is electrically connected to the terminal 686; and the conductive plate 696 has a large opening therein through which the shank of the terminal 687 extends in spaced relationship so that the conductive plate 696 is electrically insulated from the terminal 687. Similarly, the conductive plate 697 has two large openings therein through which the shanks of the respective terminals 686 and 687 extend in spaced relation therewith so that the conductive plate 697 is electrically insulated both from the terminals 686 and 687; however, the lower surface of the conductive plate 697 directly engages the upper surface of the underlying plate 688 which is connected to ground potential by the conductor N. The conductive plates 695, 696 and 697 are mutually electrically insulated from each other by the respective interposed insulators 692 and 693. Accordingly, the assembly 690 comprises a composite capacitor, including the plate 695 electrically connected to the terminal 687, the plate 696 electrically connected to the terminal 686 and the plate 697 electrically connected to ground potential. In the arrangement, the two conductive plates 695 and 696 are substantially disc-shaped and have a diameter that is approximately equal to one-eighth of the wavelength of the fundamental operating frequency of the oscillator circuit 600, whereby the microwave energy in the device 610 is bypassed to ground potential from the terminals 686 and 687. Connected to the terminal 686 and 687 are the conductors 61 and 62, respectively, whereby the assembly 690 serves to prevent introduction of microwave energy into the power supply 51 to which are connected the conductors 61 and 62.

During the operation of the oscillator 600, the anode 611 and the rods 630 within the device 610 cooperate to provide a portion of a coaxial transmission line, the coaxial transmission line thus formed being open at both ends and accommodating axially extending RF waves therein. As a consequence of this fundamental characteristic of the device 610, the oscillator 600 is formed by connecting a section of transmission line 680 between the anode 611 and the rods 630 as described above, and shorting the coaxial transmission line 680 at a point to provide a cavity that is resonant at the desired frequency of operation of the oscillator 600. More specifically, the frequen-

cy of operation of the oscillator 600 is dependent upon the length of the coaxial transmission line measured from the inner surface of the shorting wall 683 to the lower end wall 614 of the anode 611, this length of coaxial transmission line being equivalent to one-fourth of the wavelength of the operating frequency of the oscillator 600. Since the length of the thus described coaxial transmission line including the device 610 and the tuned circuit 680 is the frequency determining structure of the oscillator 600, substantially any desired frequency of operation can be achieved by simply adjusting the length of the tuned circuit 680 incorporated therein, the highest frequency being limited only by the ability to provide an RF short between the anode 611 and the rods 630 immediately adjacent to the upper ends thereof as viewed in FIG. 31.

Having arranged the parts as illustrated in FIG. 30, operation of the oscillator 600 depends only upon the application of the necessary operating potentials thereto via the conductors 60, 61 and 62. The anode current flowing from the connection 639 through the magnet coils 635 and 631 into the conductor 60 establishes the necessary unidirectional magnetic field through the interaction space 650, the field extending axially through the interaction space. The unidirectional electrical field normal to the longitudinal axis of the device 610 is created by the application of potentials to the conductors 60 and 61.

Immediately upon the application of the operating potentials to the oscillator 600, a standing RF wave is established in the tuned circuit 680 and extending into the interaction space 650. It is believed that there is associated with the RF wave an RF electrical field extending normal to the axis of the device 610 and disposed primarily between the anode 611 and the rods 630, with a small portion of the RF electrical field extending between the anode 611 and the cathode 640, and a still smaller portion of the RF electrical field extending between the rods 630 and the cathode 640. There further is believed to be associated with the standing RF wave an RF magnetic field also normal to the axis of the device 610 and likewise normal to the RF electrical field, the RF magnetic field being fundamentally disposed about and encircling the rods 630 within the anode recesses 616, and also extending inwardly into the interaction space 650 and to the cathode 640. Electrons emitted from the cathode 640 are directed into spiral paths by interaction with the fields in the interaction space 650, and during the travel of the electrons to the anode 611 and the rods 630 a portion of the energy content of the electrons is imparted to the RF standing wave to reinforce the RF standing wave and to add energy thereto. A portion of the RF standing wave is withdrawn from the oscillator 600 through the output transmission line 64, the RF energy being introduced thereto by the coupling loop 684 connected to the output transmission line 64 and disposed within the tuned cavity 680.

As has been explained above, the RF wave present within the oscillator 600 extends axially with respect to the device 610, there being no radial RF waves within the device 610, i.e., no RF waves extending normal to the axis of the device 610. Furthermore, the radial distance between the outer surface of the cathode 640 and the outermost point on the wall 618 of the recesses 616 is less than that required to accommodate a radial standing wave at the operating frequency of the oscillator 600. In fact, the radial distance between the outer surface of the cathode 640 and the outermost portion of the wall 618 of the anode recesses 616 is less than that required to accommodate a radial standing wave at an operating frequency having a wavelength corresponding to twice the distance between the ends of the anode 611, whereby there could be no radial RF standing wave even if it were possible to short the transmission line formed by the anode 611 and the rods 630 at the end walls 613 and 614 thereof.

There are illustrated in FIGS. 35 to 40 of the drawings certain operating characteristics of the crossed-field discharge device 610 illustrated in FIGS. 30 to 34 of the drawings. One

of the important features of the device 610 resides in the fact that there is but a single resonant cavity associated therewith during the operation thereof as an oscillator, whereby many of the modes of resonance encountered in a multicavity magnetron are eliminated. On the other hand, there are additional modes of operation other than that wherein the RF standing wave is disposed axially of the device 610, these additional modes propagating around the circumference of the anode, the circumferential modes of operation not being affected by the tuning of the external tuned cavity 680. There is illustrated in FIG. 35 of the drawings observed modes of this type during a cold test of the device 610, wherein microwave energy of a predetermined frequency was injected into the device 610 from a local oscillator. In obtaining the data illustrated in FIG. 35, the device 610 was provided with the resonant circuit 680 of the type illustrated in FIG. 30 so as to provide a cavity resonant at a frequency, f_0 , of 710 megacycles. It was found that the device 610 with the resonant cavity connected thereto would sustain and contain oscillations at frequencies of 690 megacycles, 845 megacycles, 1060 megacycles, 1230 megacycles, 1340 megacycles, and 1420 megacycles. The plot in FIG. 35 is of the ratio between the thus observed frequencies and the frequency f_0 plotted along the vertical axis and the mode n plotted along the horizontal axis. The observed frequencies for the various modes n are substantially the same as those calculated from the equation:

$$\frac{f}{f_0} = \sqrt{2 \left(1 - \cos \frac{2n\pi}{N} \right)}$$

wherein, f is the observed frequency at which oscillations are established in the tuned circuit, f_0 is the frequency of the tuned circuit 680, n is the mode number and N is the number of rods 630, namely, 15.

There is illustrated in FIG. 36 of the drawings the relationship between the rod current and the total current through the magnetic field coils 631 and 635 when there is a positive potential applied to the rods, a 500-ohm resistor being connected between the anode 111 and the rods 130 and an anode potential of 155 volts applied. The percent of the total current drawn through the rods is plotted along the vertical axis and the total current through the magnetic field is plotted along the horizontal axis. The low value of the rod current is believed to be due to the shielding of the rods 630 by the anode 611, it being pointed out that the rods 630 are slightly recessed with respect to the inner surfaces 617 of the anode segments 615, whereby when the cutoff field is applied, most of the electrons are collected by the anode 611.

There is illustrated in FIG. 37 of the drawings the plot of the relationship between the current drawn and the negative potential applied to the rods 630, the applied B+ potential being 100 volts. It will be seen that the current through the magnet coils 631 and 635 decreases as the negative potential upon the rods is increased.

Further characteristics of the device 610 are plotted in FIG. 38, the bias potentials being plotted along the vertical axis and the magnetic current in amperes and the corresponding magnetic field strength in gauss being plotted along the horizontal axis. The upper curve shows the effect of anode bias when a 500-ohm resistor is connected between the anode 111 and the rods 130 and the B+ potential of 155 volts is applied to the rods 130; and the lower graph shows the effect of rod bias when a 550-ohm resistor is connected between the anode 111 and the rods 130 and the B+ potential of 155 volts is applied to the anode 111.

FIGS. 39 and 40 illustrate additional characteristics of the device 610 and show the relationship between the bias applied to the rods and the corresponding current through the magnet coils, and the corresponding rod current. These curves illustrate the negative resistance phenomenon at several values of the magnetic field strength.

From the above it will be seen that there have been provided improved crossed-field discharge devices, improved microwave oscillator circuits incorporating the crossed-field

discharge devices therein, and improved amplifying circuits incorporating the crossed-field discharge devices therein which fulfill all of the objects and advantages set forth above. More particularly, there have been provided improved crossed-field discharge devices for use at microwave frequencies which are of simple and economical construction and arrangement, the devices being particularly adapted for operation with low applied potentials between the anode and cathode thereof. The improved crossed-field discharge devices provide a high output of microwave energy in proportion to the physical dimensions, whereby to permit the miniaturization of microwave circuits employing the improved crossed-field discharge devices of the present invention.

While there have been described what are at present considered to be the preferred embodiments of the invention, it will be understood that various modifications may be made therein, and it is intended to cover in the appended claims all such modifications as fall within the true spirit and scope of the invention.

20 I claim:

1. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said rods cooperating with said anode structure and said cathode structure to define the fields in said interaction space, and end structures enclosing the ends of said anode structure and said axially extending space.

2. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, both said anode segments and said rods receiving electrons from said cathode structure after passage of said electrons through said interaction space, and end structures enclosing the ends of said anode structure and said axially extending space.

3. A crossed-field discharge device comprising an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to

define an axially extending annular interaction space, said cathode structure including an electron-emissive element disposed within said anode structure and adjacent to the inner portion of said interaction space, said rods cooperating with said anode structure and said cathode structure to define the fields in said interaction space, and end structure enclosing the ends of said anode structure and said axially extending space.

4. A crossed-field discharge device comprising an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, both said anode segments and said rods receiving electrons from said cathode structure after passage of said electrons through said interaction space, and end structure enclosing the ends of said anode structure and said axially extending space.

5. A crossed-field discharge device comprising an anode structure defining an axially extending space, a plurality of axially extending anode segments on said anode structure and projecting radially into said axially extending space and providing a corresponding plurality of axially extending anode recesses therebetween, a pair of pole pieces respectively arranged adjacent to the opposite ends of said anode structure and including portions overlying and in axial alignment with said anode recesses, a plurality of rods respectively mounted on said portions of said pole pieces with the opposite ends of each rod mounted on the adjacent one of said pole pieces, each of said rods respectively extending axially in the associated one of said recesses and spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space.

6. The crossed-field discharge device set forth in claim 5, wherein said means electrically interconnecting said rods at the corresponding ends thereof is one of said pole pieces.

7. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said anode structure and said rods in the operation of said device cooperating to provide a portion of a coaxial transmission line for accommodating an axially extending RF wave therein, whereby there are RF electrical fields between said anode structure and said rods and extending inwardly into said

interaction space and having associated therewith annular RF magnetic fields about said rods and extending inwardly into said interaction space, and end structures enclosing the ends of said anode structure and said axially extending space.

8. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said anode structure and said rods in the operation of said device cooperating to provide a portion of a coaxial transmission line having the ends thereof open for accommodating an axially extending RF wave therein, whereby there are RF electrical fields between said anode structure and said rods and extending inwardly into said interaction space and having associated therewith annular RF magnetic fields about said rods and extending inwardly into said interaction space, and end structure enclosing the ends of said anode structure and said axially extending space.

9. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said rods and said cathode structure in the operation of said device cooperating to provide a portion of a coaxial transmission line for accommodating an axially extending RF wave therein, whereby there are RF electrical fields between said rods and said cathode structure and extending into said interaction space and having associated therewith annular RF magnetic fields extending into said interaction space, and end structures enclosing the ends of said anode structure and said axially extending space.

10. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, the radial distance between the outer surface of said cathode structure and the outermost portion of the adjacent one of

said anode recesses being less than that required to accommodate a radial standing wave at an operating frequency having a wavelength corresponding to twice the distance between the ends of said anode structure, and end structures enclosing the ends of said anode structure and said axially extending space.

11. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, the radial extent of said anode recesses being of the same order of magnitude as the circumferential width thereof at the inner edges of said anode segments, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space.

12. The crossed-field discharge device set forth in claim 11, wherein said anode recesses are substantially rectangular in shape as viewed along the axis of said device.

13. The crossed-field discharge device set forth in claim 11, wherein said anode recesses are substantially square as viewed in a direction axially of said device, and said rods are substantially circular in cross section.

14. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said anode structure and said pole pieces and said rods being symmetrical about a plane normal to the axis of said anode structure midway between the ends thereof, and end structures enclosing the ends of said anode structure and said axially extending space.

15. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, said anode structure and said pole pieces and said rods and said emissive element being symmetrical about a plane normal

to the axis of said anode structure midway between the ends thereof, and end structures enclosing the ends of said anode structure and said axially extending space.

16. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced electron-emissive sections corresponding in number to said anode segments and disposed within said anode structure and adjacent to the inner portion of said interaction space, both said anode segments and said rods receiving electrons from said electron-emissive sections of said cathode structure and cooperating therewith to define the fields in said interaction space, and end structures enclosing the ends of said anode structure and said axially extending space.

17. The crossed-field discharge device set forth in claim 16, wherein said electron-emissive sections are respectively arranged adjacent to one of said anode segments.

18. The crossed-field discharge device set forth in claim 16, wherein said electron-emissive sections are circumferentially spaced apart a distance corresponding generally to the circumferential dimension thereof.

19. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced protrusions corresponding in number to said anode sections and disposed within said anode structure and adjacent to the inner portion of said interaction space, at least the outermost surface portions of said protrusions being an electron-emissive material, both said anode segments and said rods receiving electrons from said electron-emissive sections of said cathode structure and cooperating therewith to define the fields in said interaction space, and end structures enclosing the ends of said anode structure and said axially extending space.

20. The crossed-field discharge device set forth in claim 19, wherein said electron-emissive portions have a circumferential extent of approximately 25 percent to 60 percent of the circumferential distance between the centers of adjacent electron-emissive portions.

21. The crossed-field discharge device set forth in claim 19, wherein the radial dimension of each of said protrusions being greater than about 20 percent of the spacing between said anode structure and said cathode structure.

22. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a

plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced electron-emissive sections corresponding in number to said anode sections and disposed within said anode structure and adjacent to the inner portion of said interaction space, said electron-emissive sections being symmetrically circumferentially located relative to said anode sections, both said anode segments and said rods receiving electrons from said electron-emissive sections of said cathode structure and cooperating therewith to define the fields in said interaction space, and end structures enclosing the ends of said anode structure and said axially extending space.

23. The crossed-field discharge device set forth in claim 22, wherein the center line of each electron-emissive section is circumferentially displaced relative to the center line of its corresponding anode segment between 0 percent and approximately 45 percent of the circumferential spacing between adjacent anode segments.

24. The crossed-field discharge device set forth in claim 22, wherein the center line of each electron-emissive section is circumferentially displaced relative to the center line of its corresponding anode segment between 25 percent and approximately 45 percent of the circumferential spacing between adjacent anode segments.

25. The crossed-field discharge device set forth in claim 22, wherein the center line of each of said electron-emissive sections is circumferentially displaced relative to the center line of its corresponding anode segment between approximately 35 percent and 45 percent of the spacing between the center lines of adjacent anode segments and on the downstream side of the corresponding anode segment relative to the normal initial electron flow from said electron-emissive sections to said anode segments in said device.

26. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced electron-emissive sections corresponding in number to the sum of the number of said anode sections and the number of said rods and disposed within said anode structure and adjacent to the inner portion of said interaction space, and end structures enclosing the ends of said anode structure and said axially extending space.

27. The crossed-field discharge device set forth in claim 26, wherein said electron-emissive sections are equal in number to the sum of the number of said anode sections and the number of said rods and are respectively arranged adjacent to the corresponding one of said anode segments and said rods.

28. The crossed-field discharge device set forth in claim 26, wherein said electron-emissive sections are circumferentially spaced apart a distance corresponding generally to the circumferential dimension thereof.

29. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding

plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced protrusions corresponding in number to the sum of the number of said anode sections and the number of said rods and disposed within said anode structure and adjacent to the inner portion of said interaction space, at least the outermost surface portions of said protrusions being an electron-emissive material, and end structures enclosing the ends of said anode structure and said axially extending space.

30. The crossed-field discharge device set forth in claim 29, wherein said electron-emissive portions have a circumferential extent of approximately 25 percent to 60 percent of the circumferential distance between the centers of adjacent electron-emissive portions.

31. The crossed-field discharge device set forth in claim 29, wherein the radial dimension of each of said protrusions is greater than about 20 percent of the spacing between said anode structure and said cathode structure.

32. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a plurality of circumferentially spaced electron-emissive sections equal in number to the sum of the number of said anode sections and the number of said rods and disposed within said anode structure and adjacent to the inner portion of said interaction space, said electron emissive sections being symmetrically circumferentially located relative to the associated anode sections and rods, and end structures enclosing the ends of said anode structure and said axially extending space.

33. The crossed-field discharge device set forth in claim 32, wherein the centerline of each electron-emissive section is circumferentially displaced relative to the center line of the corresponding one of said anode segments and said rods between 0 percent and approximately 45 percent of the circumferential spacing between the centerline of an anode segment and the centerline of an adjacent rod.

34. The crossed-field discharge device set forth in claim 32, wherein the centerline of each electron-emissive section is circumferentially displaced relative to the centerline of the corresponding one of said anode segments and said rods between 25 percent and approximately 45 percent of the circumferential spacing between the center line of an anode segment and the centerline of an adjacent rod.

35. The crossed-field discharge device set forth in claim 32, wherein the centerline of each electron-emissive section is circumferentially displaced relative to the center line of the corresponding one of said segments and said rods between approximately 35 percent and 45 percent of the spacing between the centerline of an anode segment and the centerline of an adjacent rod and on the downstream side of the corresponding anode segment or rod relative to the normal initial electron flow from said electron emissive sections toward said anode segments and said rods in said device.

36. A crossed-field discharge device comprising an anode structure defining an axially extending space, a pair of pole

pieces respectively arranged adjacent to the opposite ends of said anode structure, a plurality of axially extending anode segments on said anode structure projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a conically shaped electron-emissive element disposed within said anode structure and adjacent to the inner portion of said interaction space and extending substantially the length thereof with the axis of said emissive element extending axially of said device, and end structures enclosing the ends of said anode structure and said axially extending space.

37. The crossed-field discharge device set forth in claim 36, wherein said emissive element is shaped as a section of a regular right cone having the ends thereof disposed within the ends of said anode structure.

38. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, end structures enclosing the ends of said anode structure and said axially extending space, and an output connector for said rods having one end thereof connected to said rods and the other end thereof extending outwardly through one of said end structures.

39. A crossed-field discharge device comprising an anode structure defining an axially extending space, a pair of pole pieces respectively arranged adjacent to the opposite ends of said anode structure, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, end structures enclosing the ends of said anode structure and said axially extending space, and a pair of output connectors for said rods, one of said connectors having one end thereof connected to corresponding one ends of said rods and the other end thereof extending outwardly through one of said end structures and the other of said connectors having one end thereof connected to the corresponding other ends of said rods and the other end thereof extending outwardly through the other one of said end structures.

40. A crossed-field discharge device comprising an anode structure defining an axially extending space, a plurality of axially extending anode segments on said anode structure and projecting radially into said axially extending space and providing a corresponding plurality of axially extending anode

recesses therebetween, a pair of pole pieces respectively arranged adjacent to the opposite ends of said anode structure and including projections overlying and in axial alignment with said anode recesses, a plurality of rods having corresponding ends thereof mounted on the projections on one of said pole pieces and electrically interconnected thereby, said rods respectively extending axially in said anode recesses and respectively spaced from the adjacent ones of said anode segments, an axially extending cathode structure disposed in said axially extending space and cooperating with said anode structure to define an axially extending annular interaction space, said cathode structure including an electron-emissive element disposed within said anode structure and adjacent to the inner portion of said interaction space, end structures enclosing the ends of said anode structure and said axially extending space, and an output connector for said rods having one end thereof connected to said one pole piece and the other end thereof extending outwardly through one of said end structures.

41. A crossed-field discharge device comprising an anode structure defining an axially extending space, a plurality of axially extending anode segments on said anode structure and projecting radially into said axially extending space and providing a corresponding plurality of axially extending anode recesses therebetween, a pair of pole pieces respectively arranged adjacent to the opposite ends of said anode structure and including portions overlying and in axial alignment with said anode recesses, a plurality of rods having the opposite ends thereof mounted on said portions on said pole pieces and extending axially therebetween and being electrically interconnected thereby, said rods respectively extending axially in said anode recesses and respectively spaced from adjacent ones of said anode segments, an axially extending cathode structure disposed in said axially extending space and cooperating with said anode structure to define an axially extending annular interaction space, said cathode structure including an electron-emissive element disposed within said anode structure and adjacent to the inner portion of said interaction space, end structures enclosing the ends of said anode structure and said axially extending space, and a pair of output connectors for said rods, one of said connectors having one end thereof connected to one of said pole pieces and the other end thereof extending outwardly through one of said end structures and the other of said connectors having one end thereof connected to the other of said pole pieces and the other end thereof extending outwardly through the other of said end structures.

42. A microwave oscillator comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, both said anode segments and said rods receiving electrons from said cathode structure and cooperating therewith to define the fields in said interaction space, and end structures enclosing the ends of said anode structure and said axially extending space; means for producing a unidirectional magnetic field extending axially through said interaction space; means for producing a unidirectional electrical field between said anode structure and said cathode structure; and a resonant circuit coupled between said anode structure and said rods for determining the frequency of operation of said oscillator.

43. A microwave oscillator comprising a crossed-field discharge device including an anode structure defining an axi-

49. A microwave oscillator comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, both said anode segments and said rods receiving electrons from said cathode structure and cooperating therewith to define the fields in said interaction space, and end structures enclosing the ends of said anode structure and said axially extending space; means for producing a unidirectional magnetic field extending axially through said axially extending space; means for producing a unidirectional electrical field between said rods and said cathode structure; and a resonant circuit coupled between said rods and said cathode structure for determining the frequency of operation of said oscillator.

50. A microwave oscillator comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; means for producing a unidirectional magnetic field extending axially through said axially extending space; means for producing a unidirectional electrical field between said rods and said cathode structure; and a resonant circuit coupled between said rods and said cathode structure for determining the frequency of operation of said oscillator, said resonant circuit being of the coaxial conductor type and having an electrical wavelength corresponding to one-half of the wavelength of the resonant frequency thereof.

51. A microwave oscillator comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; means for producing a unidirectional magnetic field extending axially through said axially extending space; means for producing a unidirectional electrical field between said rods and said cathode structure; and a resonant circuit coupled between said rods and said cathode structure for determining the frequency of operation

of said oscillator, said resonant circuit being of the coaxial conductor type and having an electrical wavelength corresponding to one-quarter of the wavelength of the resonant frequency thereof.

52. A microwave oscillator comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; means for producing a unidirectional magnetic field extending axially through said axially extending space; means for producing a unidirectional electrical field between said rods and said cathode structure; and a resonant circuit coupled between said rods and said cathode structure for determining the frequency of operation of said oscillator, and means for tuning said resonant circuit.

53. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; a microwave input coupled between said anode structure and said rods at one end of said device; a microwave output coupled between said anode structure and said rods at the other end of said device; means for producing a unidirectional magnetic field extending axially through said axially extending space; and means for producing a unidirectional electrical field between said anode structure and said cathode structure; whereby a microwave signal fed to the input of said amplifier at said one end of said device is amplified thereby and the amplified microwave signal appears at the output of said amplifier at the other end of said device.

54. The microwave amplifier set forth in claim 53, and further comprising means for providing a bias between said anode structure and said rods.

55. The microwave amplifier set forth in claim 53, and further comprising means for providing a bias between said cathode structure and said rods.

56. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an elec-

tron-emissive element disposed within said anode structure and adjacent to the inner portion of said interaction space, and end structures enclosing the ends of said anode structure and said axially extending space; a coaxial transmission line including an outer conductor and an inner conductor disposed within said outer conductor, one end of said outer conductor being coupled to said anode structure at one end of said device, the corresponding one end of said inner conductor being coupled to said rods at said one end of said device, and means shorting said inner conductor to said outer conductor at a point spaced from a plane midway between the ends of said anode structure a distance equal to approximately three-fourths of the wavelength of the microwave energy to be amplified by said device; a microwave input coupled to said coaxial transmission line adjacent to the shorted end thereof; a microwave output coupled between said anode structure and said rods at the other end of said device; means for producing a unidirectional magnetic field extending axially through said axially extending space, and means for producing a unidirectional electrical field between said anode structure and said cathode structure; whereby a microwave signal fed to the input of said amplifier at said one end of said device is amplified thereby and the amplified microwave signal appears at the output of said amplifier at the other end of said device.

57. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; a first coaxial transmission line including a first outer conductor and a first inner conductor disposed within said first outer conductor, one end of said first outer conductor being coupled to said anode structure at one end of said device, the corresponding one end of said first inner conductor being coupled to said rods at said one end of said device, means shorting said first inner conductor to said first outer conductor at a point spaced from a plane midway between the ends of said anode structure a distance equal to approximately three-fourths of the wavelength of the microwave energy to be amplified by said device; a microwave input coupled to said first coaxial transmission line adjacent to the shorted end thereof; a second coaxial transmission line including a second outer conductor and a second inner conductor disposed within said second outer conductor, one end of said second outer conductor being coupled to said anode structure at the other end of said device, the corresponding one end of said second inner conductor being coupled to said rods at said other end of said device; and a microwave output coupled between the said second outer conductor and said second inner conductor; means for producing a unidirectional magnetic field extending axially through said axially extending space; and means for producing a unidirectional electrical field between said anode structure and said cathode structure; whereby a microwave signal fed to the input of said amplifier at said one end of said device is amplified thereby and the amplified microwave signal appears at the output of said amplifier at the other end of said device.

58. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including an electron-emissive element disposed within said anode structure and adjacent to the inner portion of said interaction space, and end structures enclosing the ends of said anode structure and said axially extending space; a first coaxial transmission line including a first outer conductor and a first inner conductor disposed within said first outer conductor, one end of said first outer conductor being coupled to said anode structure at one end of said device, the corresponding one end of said first inner conductor being coupled to said rods at said one end of said device, means shorting said first inner conductor to said first outer conductor at a point spaced from a plane midway between the ends of said anode structure a distance equal to approximately three-fourths of the wavelength of the microwave energy to be amplified by said device; a microwave input coupled to said first coaxial transmission line adjacent to the shorted end thereof; a second coaxial transmission line including a second outer conductor and a second inner conductor disposed within said second outer conductor, one end of said second outer conductor being coupled to said anode structure at the other end of said device, the corresponding one end of said second inner conductor being coupled to said rods at said other end of said device; and a microwave output coupled between the said second outer conductor and said second inner conductor; means for producing a unidirectional magnetic field extending axially through said axially extending space; and means for producing a unidirectional electrical field between said anode structure and said cathode structure; whereby a microwave signal fed to the input of said amplifier at said one end of said device is amplified thereby and the amplified microwave signal appears at the output of said amplifier at the other end of said device.

59. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a conically shaped electron-emissive element disposed within said anode structure and adjacent to the inner portion of said interaction space with the axis of said element extending axially of said device, and end structures enclosing the ends of said anode structure and said axially extending space; a microwave input coupled between said anode structure and said rods at the end of said device adjacent to the smaller end of said element; a microwave output coupled between said anode structure and said rods at the end of said device adjacent to the larger end of said element; means for producing a unidirectional magnetic field extending axially through said axially extending space; and means for producing a unidirectional electrical field between said anode structure and said cathode structure; whereby the microwave signal fed to the input of said amplifier is amplified thereby and the amplified microwave signal appears at the output of said amplifier at the other end of said device.

60. The microwave amplifier set forth in claim 59, and further comprising means for providing a bias between said anode structure and said rods at the end of said device adjacent to the smaller end of said electron-emissive element.

61. The microwave amplifier set forth in claim 59, and further comprising means for providing a bias between said cathode structure and said rods at the end of said device adjacent to the smaller end of said electron-emissive element.

62. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a conically shaped electron-emissive element disposed within said anode structure and adjacent to the inner portion of said interaction space with the axis of said element extending axially of said device, and end structures enclosing the ends of said anode structure and said axially extending space; a coaxial transmission line including an outer conductor and an inner conductor disposed within said outer conductor, one end of said outer conductor being coupled to said anode structure at the end of said device adjacent to the smaller ends of said element, the corresponding one end of said inner conductor being coupled to said rods at the end of said device adjacent to the smaller end of said element, and means shorting said inner conductor to said outer conductor at a point spaced from a plane midway between the ends of said anode structure a distance equal to approximately three-fourths of the wavelength of the microwave energy to be amplified by said device; a microwave input coupled to said coaxial transmission line adjacent to the shorted end thereof; a microwave output coupled between said anode structure and said rods at the end of said device adjacent to the larger end of said element; means for producing a unidirectional magnetic field extending axially through said axially extending space; and means for producing a unidirectional electrical field between said anode structure and said cathode structure; whereby the microwave signal fed to the input of said amplifier is amplified thereby and the amplified microwave signal appears at the output of said amplifier.

63. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a conically shaped electron-emissive element disposed within said anode structure and adjacent to the inner portion of said interaction space with the axis of said element extending axially of said device, and end structures enclosing the ends of said anode structure and said axially extending space; a first coaxial transmission line including a first outer conductor and a first inner conductor disposed within said first outer conductor, one end of said first outer conductor being coupled to said anode structure at the end of said device adjacent to the smaller end of said element, the corresponding one end of said first inner conductor being coupled to said rods at the end of said device adjacent to the smaller end of said element, and means shorting said first inner conductor to said first outer conductor at a point spaced from a plane midway between the ends of said anode structure a distance equal to approximately three-fourths of the wavelength of the microwave energy to be amplified by said device; a microwave input coupled to said transmission line adjacent to the shorted end thereof; a second coaxial transmission line including a second outer conductor and a second inner conductor disposed within said second outer conductor, one end of said second outer conductor being coupled to said anode structure at the end of said device adjacent to the larger end of said element, the corresponding one end of said second inner conductor being coupled to said rods at the end of said device adjacent to the larger end of said element; means for producing a unidirectional magnetic field extending axially through said axially extending space; and means for producing a unidirectional electrical field between said anode structure and said cathode structure; whereby the microwave signal fed to the input of said amplifier is amplified thereby and the amplified microwave signal appears at the output of said amplifier.

conductor at a point spaced from a plane midway between the ends of said anode structure a distance equal to approximately three-fourths of the wavelength of the microwave energy to be amplified by said device; a second coaxial transmission line including a second outer conductor and a second inner conductor disposed within said second outer conductor, one end of said second outer conductor being coupled to said rods at the end of said device adjacent to the smaller end of said element, the corresponding one end of said second inner conductor

10 being coupled to said cathode structure at the end of said device adjacent to the smaller end of said element, and means shorting said second inner conductor to said second outer conductor at a point spaced from a plane midway between the ends of said anode structure a distance equal to more than three-fourths of the wavelength of the microwave energy to be amplified by said device; a microwave input coupled to said first coaxial transmission line adjacent to the shorted end thereof; a microwave output coupled between said anode structure and said rods at the end of said device adjacent to the larger end of said element; means for producing a unidirectional magnetic field extending axially through said axially extending space; and means for producing a unidirectional electrical field between said anode structure and said cathode structure; whereby the microwave signal fed to the input of said amplifier is amplified thereby and the amplified microwave signal appears at the output of said amplifier.

64. A microwave amplifier comprising a crossed-field discharge device including an anode structure defining an axially extending space, a plurality of axially extending anode segments on said anode structure and projecting radially into said axially extending space and providing a corresponding plurality of axially extending anode recesses therebetween, a plurality of rods respectively disposed in said anode recesses and respectively spaced from the adjacent ones of said anode segments, means electrically interconnecting said rods at corresponding ends thereof, an axially extending cathode structure disposed in said axially extending space and cooperating with said anode structure to define an axially extending annular interaction space, said cathode structure including a conically shaped electron-emissive element disposed within said anode structure and adjacent to the inner portion of said interaction space with the axis of said element extending axially of said device, and end structures enclosing the ends of said anode structure and said axially extending space; a first coaxial transmission line including a first outer conductor and a first inner conductor disposed within said first outer conductor, one end of said first outer conductor being coupled to said anode structure at the end of said device adjacent to the smaller end of said element, the corresponding one end of said first inner conductor being coupled to said rods at the end of said device adjacent to the smaller end of said element, and means shorting said first inner conductor to said first outer conductor at a point spaced from a plane midway between the ends of said anode structure a distance equal to approximately three-fourths of the wavelength of the microwave energy to be amplified by said device; a microwave input coupled to said transmission line adjacent to the shorted end thereof; a second coaxial transmission line including a second outer conductor and a second inner conductor disposed within said second outer conductor, one end of said second outer conductor being coupled to said anode structure at the end of said device adjacent to the larger end of said element, the corresponding one end of said second inner conductor being coupled to said rods at the end of said device adjacent to the larger end of said element; means for producing a unidirectional magnetic field extending axially through said axially extending space; and means for producing a unidirectional electrical field between said anode structure and said cathode structure; whereby the microwave signal fed to the input of said amplifier is amplified thereby and the amplified microwave signal appears at the output of said amplifier.

UNITED STATES PATENT OFFICE
CERTIFICATE OF CORRECTION

Patent No. 3,551,735 Dated December 29, 1970

Inventor(s) JAMES E. STAATS

It is certified that error appears in the above-identified patent and that said Letters Patent are hereby corrected as shown below:

Column 42, Claim 8, line 30, change "structure", (first occurrence) to -- structures --.

Column 43, Claim 13, line 34, change "sad" to -- said --.

Column 50, Claim 46, line 7, change "respective" to -- respectively --.

Column 50, Claim 46, line 20, delete "space;" (first occurrence line 20, delete "magnetic" and insert -- unidirectional magnetic field extending axially through said axially extending space; means for producing a --.

Signed and sealed this 27th day of April 1971.
